TELEPHONE SYSTEM

Imre Molnar, Chicago, Ill., assignor to Associated Electric Laboratories, Inc., Chicago, Ill., a corporation of Delaware

Application December 29, 1939, Serial No. 311,546

57 Claims. (Cl. 179—27)

The present invention relates to telephone systems and more particularly to improvements in apparatus for handling branch exchange calls of a special character.

As explained in Patent No. 1,816,634, Carpenter et al., granted July 28, 1931, and Patent No. 1,841,093, Dahl, granted January 12, 1932, in certain branch exchange installations a large part of the incoming calls are of a special character. For example, in large department stores a major portion of the incoming calls are for the purpose of placing orders or represent requests for information concerning the price of the merchandise on sale. In order more expeditiously to handle the calls incoming to a branch exchange of this type it is desirable to segregate the calls of special character from the other calls and to route the calls of special character to special information or order operators' positions, which positions are staffed with attendants qualified to dispatch the desired information. In the two patents cited above, apparatus is provided for the general purpose just mentioned, the arrangement being such that all of the calls of special character are first stored in a call storage circuit and are then released from storage to the special operators' positions in the same order as they are stored. This arrangement not only requires an extremely complicated and extensive switching arrangement in association with the special operators' positions, but is open to the objection that the calls are delayed somewhat due to the extensive switching operations required to first store the calls and then release the calls from storage.

It is an object of the present invention, therefore, to provide in a telephone system improved special call handling facilities of the character described which are of simple and economical arrangement, are positive and reliable in operation and are so arranged that the special calls are normally routed directly to the special operators' positions so long as any of the special operators' positions are idle.

It is another object of the invention to provide improved special call handling facilities of the character described wherein provisions are made for storing the special calls only when the number of special calls existing at any one time exceeds the call handling capacity of the special operators' positions.

It is a further object of the invention to provide improved special call handling facilities of the character described wherein the call storage circuit is so arranged that the excess stored calls

are released from storage and routed to the special operators' positions in the same order as they were stored.

It is another object of the invention to provide 5 an improved call storage arrangement wherein exceedingly simple provisions are made for positively preventing undue delay in releasing calls from storage and for normally preventing excess calls from obtaining preferred storage positions.

10 It is a further object of the invention to provide a call storage circuit of the character described which is so arranged that excess calls may be permitted to obtain preferred storage positions, whereby under certain conditions of 15 heavy traffic all of the available call storage positions of the circuit may be utilized.

It is still another object of the invention to provide in a telephone system, improved special 20 call handling facilities of the character described wherein provisions are made for readily transferring the calls of special character from the special operators' positions to the regular branch exchange switchboard and for routing calls directly from the special operators' positions to 25 the branch exchange switchboard.

It is a still further object of the invention to provide in a telephone system including special 30 call handling facilities of the character described, an improved arrangement whereby all of the special call trunks, the call storage circuit and the special operators' positions may be supervised from a supervisory operator's position and the call storage apparatus may be controlled from the supervisory operator's position.

35 In the illustrated embodiment of the invention, there is provided a telephone system which comprises a central exchange and a branch exchange area including regular branch exchange facilities. These facilities comprise the usual

40 branch exchange switchboard at which are terminated a plurality of trunks which extend to switching equipment in the central exchange. The system further comprises additional apparatus which is adapted to handle the calls of special character routed from the central exchange to the branch exchange area. This additional apparatus comprises a plurality of special operators' positions and a plurality of special call trunks which extend from the central exchange and terminate in the branch exchange area in trunk circuits, each of which includes a position 45 finder having access to all of the special operators' positions. The arrangement of the trunk circuit apparatus is such that calls originating on the associated trunks in the central exchange are

automatically routed through the associated position finders directly to idle ones of the special operators' positions so long as any of these positions are idle. For the purpose of storing excess or overflow calls until such time as special operators' positions are available, there is provided a call storage circuit which is commonly associated with the various trunk circuits and includes a call storage position distributor and call storage release means. In order to permit the transfer of special calls from the special operators' positions to the regular branch exchange switchboard, a plurality of transfer trunks are provided, which extend from the trunk circuits just mentioned to the branch exchange operator's switchboard. The transfer trunks are utilized solely to transfer incoming special calls to the branch exchange operator's switchboard, an additional group of trunks being provided for enabling the special operators to extend calls from their respective positions to the regular branch exchange switchboard. More specifically, the additional trunks, just mentioned, individually terminate in position finder switches which have access to the special operators' positions and have commonly associated therewith a distributor which functions to allot the position finders and associated trunks for use in a predetermined order.

The arrangement of the call storage circuit and of the associated trunk circuits individual to the special call trunks is such that stored calls are released from storage in the same order as they are stored. More particularly, each of the trunk circuits is provided with a storage position finder having positions individually corresponding to the storage positions of the storage position distributor and the call release positions of the storage release means. The arrangement is such that the storage finders are operated in response to calls initiated on the associated trunks when all of the special operators' positions are busy, means controlled by the storage distributor being provided for stopping the storage finders in different positions whereby the excess calls are stored in a predetermined order. Additional apparatus controlled jointly by the storage release means and the storage position finders and operative in accordance with the settings of the storage finders, are provided for routing the stored calls to the special operators' positions in the same predetermined order as the special operators' positions are released or become idle. In order to prevent any unnecessary elapse of time in releasing calls from storage, control apparatus is provided for preventing the storage release means from operating through a position occupied by the position of the storage position distributor. Additional control apparatus is provided for normally preventing the storage position distributor from operating through a position occupied by the storage release means, thereby to prevent later initiated special calls from obtaining preferred storage positions. The arrangement is such that the last-mentioned control apparatus may be rendered inactive, whereby storage positions of the storage distributor which correspond to abandoned stored calls may be utilized in storing additional calls. More specifically, the last-mentioned control apparatus is under the control of a supervisory operator whose function it is to maintain supervision of the various special operators' positions and the special call trunks having access to these positions. To this end, various supervisory lamps are provided at the supervisory operator's position and provi-

sions are made whereby the supervisory operator may monitor any connection established to any one of the special operators' positions. Among the supervisory lamps provided at the supervisory operator's position are included a group of call storage lamps which are individual to the several special call trunks, the arrangement being such that each of these lamps is energized when a call, present on the associated trunk, is placed in storage. Further, the control arrangement for the call storage lamps is such that each lamp is deenergized when a call stored on the associated trunk is abandoned prior to its release from storage. By virtue of this arrangement, the supervisory operator may maintain a close check upon the number of calls in storage and ascertain the advisability of utilizing vacated call storage positions of the call storage distributor to store additional calls.

Further features of the invention pertain to the particular arrangement of the circuit elements whereby the above-outlined and additional operating features are attained.

The novel features believed to be characteristic of the invention are set forth with particularity in the appended claims. The invention, both as to its organization and method of operation, together with further objects and advantages thereof will best be understood by reference to the specification taken in connection with the accompanying drawings in which Figure 1 schematically illustrates a telephone system having incorporated therein the features of the invention as briefly outlined above; Fig. 2 illustrates the manner of assembling the remaining figures of the drawings to form a unified system; and Figs. 3 to 6, inclusive, illustrate the details of the apparatus schematically shown in Fig. 1.

Referring now more particularly to Fig. 1 of the drawings, the telephone system there illustrated comprises a central exchange 10 and a branch exchange area 20 within which are located the substations of a department store, or the like. The central exchange 10 may be of any desired type; that is, it may be of the manual type, in which case, the subscribers' and trunk lines extending thereto are terminated in line multiples at the operators' switchboard in the usual manner. Alternatively, the exchange 10 may be of any desired automatic type, in which case, connections are established between the lines extending thereto through the provision of dial controlled automatic switching apparatus. This exchange is arranged to serve a large number of central office subscribers' lines, one of which is indicated at 11 as extending to the central office subscriber's substation A. For the purpose of routing regular substation-to-substation calls between the central office and the branch exchange area 20 there are provided a plurality of branch exchange trunks, one of which is indicated at 12. This trunk has a trunk circuit 13 of conventional arrangement associated therewith and terminates at a jack 14 which is provided at one of the operators' positions forming a part of the branch exchange operator's switchboard. This switchboard is provided for the purpose of serving the regular branch exchange substations located within the area 20, one such substation B being connected to a substation line 15 which terminates at the branch exchange switchboard in a jack 17 and has associated therewith a line circuit 16 through opera-

tion of which calls involving the line 15 may be supervised.

In order to handle calls of special character routed from the central office subscribers' substations through the central exchange 10 to the branch exchange area 20, a plurality of special call trunks, one of which is indicated at 18, are provided. Assuming that the central exchange 10 is of the manual type, these trunks extend from the operator's switchboard in the central exchange 10 to the branch area 20 where they terminate in trunk circuits individual thereto. These trunk circuits have access to a group of special operators' positions. In the case under consideration wherein it is assumed, for purposes of explanation, that the branch exchange area 20 constitutes a department store or other merchandise establishment, the special operators' positions may be provided for the purpose of taking orders from the central office subscribers. For convenience in describing the apparatus, the special call trunks will be referred to hereinafter as order trunks, the trunk circuits associated therewith will be referred to as order trunk circuits, and the special operators' positions will be referred to as order operators' positions. More specifically, the order trunk 18 terminates in the branch exchange area 20 in an order trunk circuit 19 which has access to a group of order operators' positions including the position 21. Under certain circumstances and, more particularly, when all of the order operators' positions are not staffed, the volume of traffic over the order trunks may be in excess of the call handling capacity of those order operators' positions which are attended. In order to hold such excess calls until such time as an order operator's position is released, there is provided, in common association with the several order trunk circuits, a call storage circuit 31 which functions to store the excess calls in the order of their initiation and to release the stored calls from storage in the same order, as the order operators' positions become idle. For the purpose of enabling the order operators to transfer calls from their positions to the branch exchange switchboard, whereby they may be extended to the regular branch exchange substations, there are provided a group of transfer trunks, one of which is indicated at 22 as extending from the order trunk circuit 19 to a jack 23 located at the branch exchange operator's switchboard. This group of trunks can only be used for transfer purposes. Accordingly, additional means comprising a second group of trunks including the trunk 26 is provided for enabling the order operators to route calls directly from their positions to the branch exchange switchboard. More specifically, these additional trunks terminate in position finders which have access to the various order operators' positions and have associated therewith a position finder distributor 30 which functions to allot the additional trunks and associated position finders for use in a predetermined order. Thus, the trunk 26 terminates at the branch exchange switchboard in a jack 28 and extends to a position finder 29 having access to all of the order operators' positions. For the purpose of supervising calls routed by way of the order trunks to the order operators' positions there is provided a supervisory operator's position 32 at which are located signal lamps for indicating whether or not the order operators' positions are staffed and, if staffed, whether idle or busy, and also for identifying those of the 75

order trunks which are occupied with calls in storage.

Neglecting for the present the particular arrangement of the circuit elements embodied in the apparatus schematically illustrated in Fig. 1 and considering the operation of the system generally, it will be apparent that interexchange traffic between the central office subscribers' substations and the regular substations provided in the branch exchange area 20 are handled by the regular branch exchange facilities including the branch exchange operator's switchboard and the group of trunks of which the trunk 12 forms a part. To this end, the branch exchange operator's switchboard is assigned a particular directory number which is different from the directory number assigned to the order operators' positions. By virtue of this directory numbering scheme the special or order trunk calls may be segregated in the central exchange and routed by way of the order trunks to idle ones of the order operators' positions. For example, a call routed over the order trunk 18 may, through operation of the order trunk circuit 19, be routed to the order operator's position 21. If the order operator attending this position is unable to give the calling subscriber the desired information, she may cause the call to be transferred to one of the regular substations provided in the branch exchange area 20 by operating a transfer key located at her position, thereby to signal over the transfer trunk 22 the branch exchange operator attending the position at which the trunk 22 is terminated. The branch exchange operator may, in turn, route the call to the desired substation, such, for example, as the substation B. After a call transfer of this character is made the order operator attending the position 21 may remain connected to the established three-way connection or may retire from the connection and release her position for utilization in the handling of additional calls. If an operator attending one of the order operators' positions, such, for example, as the position 21, finds it necessary in handling an inquiry to look up certain information and then call a central office subscriber, she may secure the desired connection by seizing one of the trunks assigned for use by the position finder distributor 30, such, for example, as the trunk 26, thereby to route a connection from her position to a position at the branch exchange switchboard. From this latter position the call may be routed over one of the regular branch exchange trunks and through the central exchange 10 to the desired substation. In a similar manner the order operators may route calls directly from their positions to the regular substations located in the branch exchange area, such calls being handled by the operator or operators attending the branch exchange switchboard. In the event all of the order operators' positions become busy at the same time and special calls routed over the order trunks continue to arrive, operation of the call storage circuit 31 is initiated whereby the excess calls are stored in the order of their initiation. As the order operators' positions are thereafter released and rendered available for use in handling other calls, the call storage circuit 31 in cooperation with the associated trunk circuits functions to release the stored calls from storage in the same order as they are stored. Supervision of the order operators' positions and of the special calls handled at these positions is under the control of a supervisory operator attending the position 32.

Referring now in greater detail to the circuit arrangement of the apparatus schematically illustrated in Fig. 1 and considering first the order trunk circuit 18, this circuit is illustrated in Figs. 3 and 4 as comprising an operator's position finder switch 400, a storage position finder switch 360 and a plurality of associated control relays and control circuits. The switches 360 and 400 are of the well-known rotary type and may be of any desired commercial construction. The number of contact points provided in the position finder switch 400 is determined by the number of available order operators' positions, each setting of this switch being individual to a particular order operator's position. Similarly, the number of contact points provided in the storage position finder switch 360 is determined by the number of storage positions available in the call storage circuit 31. In the arrangement illustrated, twenty-four call storage positions are available in this circuit and hence twenty-five sets of contact points are provided in the rotary switch 360, the first set of contact points being reserved as the normal or home position of this switch. The control equipment associated with the two switches 360 and 400 comprises a line relay R300 which is normally bridged across the conductors of the order trunk 18 in series with a condenser 317 and is arranged to operate when energized with either alternating or direct current. This equipment further comprises a slow-to-operate position finder start relay R310, a pair of call storage control relays R320 and R330, a combined call transfer and trunk release relay R340 which is provided with two operating positions in addition to its normally released position, and a combined finder stop and line switching relay R350.

The apparatus provided at the order operator's position 21 comprises an induction coil 451 which is connected to a pair of talking conductors C492 and C493, these conductors being terminated in corresponding sets of contacts in the position finder switches individual to the various trunk circuits. This induction coil has connected thereto transmitter and receiver jacks 413 and 414, respectively, which are arranged to receive the contacts of a multiple plug 412. The contacts of this plug are connected in the usual manner to a transmitter 411 and a receiver 412 forming an operator's head set. There is also provided at the operator's position 21 a relay R430, which is operative to indicate that the position is staffed, and a slow-to-operate control relay R440. The latter relay is arranged to control the energization of a call signal lamp 423 and to perform other control operations described hereinafter. The control equipment provided at the order operator's position 21 also includes a combined call transfer and trunk circuit release key 416 and a branch exchange call key 420, the first of these keys being operative to control the transfer of calls from the position 21 to the branch exchange switchboard and to control the release of trunk circuits which are operated when calls are routed by way thereof to the position 21. The key 420, on the other hand, is provided for the purpose of routing calls from the order operator's position 21 directly to the branch exchange switchboard.

As illustrated in the right-hand portion of Fig. 4, the position finder 29, which is individual to the trunk 26 extending to the branch exchange switchboard, comprises a finder switch 450 of the well-known rotary type and a line switching re-

lay R460. The number of contact points provided in the finder switch 450 is determined by the number of associated order operators' positions, one set of contact points being reserved for each of the order operators' positions to which it has access. Operation of this position finder and of the other finders individually associated with the other trunks extending to the branch exchange switchboard is under the control of the position finder distributor 30 which is illustrated in Fig. 6 as comprising a distributor switch 640, also of the well-known rotary type, and having positions corresponding to the number of position finders available. This distributor also includes a plurality of control relays which may be identified as a slow-to-operate start relay R610, a pulsing relay R630, a relay R620 for controlling the line switching relays of the respective associated position finders, and a slow-to-release relay R600 which is operative to delay the trunk hunting operation of the distributor switch 640 for a short time interval after a previously selected position finder switch is operated to seize a calling one of the order operators' positions.

As pointed out previously, the apparatus provided at one of the branch exchange operators' positions forming a part of the branch exchange switchboard comprises the jacks 17, 28, 14 and 23 at which the lines 15, 26, 12 and 22, respectively terminate. These lines have individually associated therewith call signal lamps 666, 663, 665 and 653, respectively. There is also provided at this branch exchange operator's position an operator's cord circuit 660 which may be of conventional arrangement. This cord circuit is connected to call and answer plugs 662 and 661, respectively, and includes a transmitter 670 and a receiver 671.

The call storage circuit 31 is illustrated in Fig. 5 as comprising a call storage distributor switch 500 and a call release switch 510 each of which is of the well-known rotary type and includes twenty-five sets of contact points respectively representing twenty-four different call storage positions and a blank or unused position. The operation of these switches is under the control of associated relay equipment which comprises a call storage start relay R540, a call storage stop relay R530, and a pulsing relay network for the rotary switch 510 which includes the relay R520 and the slow-to-release relay R570. A second slow-to-operate pulsing relay R560 is provided for controlling the operation of the distributor switch 500. The relay equipment also includes a stop relay R550 which functions to prevent the rotary switch 510 from operating to a storage position in advance of that occupied by the distributor switch 500 all in the manner more fully explained hereinafter. For the purpose of indicating an all-busy condition of the order trunks, there is provided an all-trunks-busy meter 522.

The apparatus provided at the supervisory operator's position 32 comprises a plurality of jacks at which are terminated trunk lines bridged across the talking conductors provided in the various order operators' positions. Thus, a jack 491 is provided which is connected to the conductors C492 and C493 constituting the talking conductors provided at the order operator's position 21. There are also provided at the supervisory operator's position 32 a plurality of signal lamps individual to the order operators' positions and to the order trunks which enable the super-

visory operator to check at all times the condition of the trunks and of the order operators' positions. Thus, a position lamp 425 is provided which is individual to the order operator's position 21 and which, when energized, indicates that this order operator's position is attended. A second lamp 424 individual to the order operator's position 21 is also provided which, when energized, indicates that the associated position is busy. A third signal lamp 426 is provided which is individual to the order trunk 18 and functions, when energized, to indicate that the associated order trunk is occupied with a call which has been placed in storage. In order to enable the supervisory operator to control the call storage circuit 31 in accordance with the conditions indicated by the energized and deenergized conditions of the associated trunk call storage lamps, there are provided two keys 421 and 422, the last of which is operative to render the call storage circuit 31 totally inactive. The key 421, on the other hand, is provided for the purpose of enabling the storage distributor switch 500 to be advanced through a position occupied by the call release switch 510, thereby to permit those call storage positions in the switch 500 which have been vacated through the abandonment of stored calls to be filled up with additional incoming calls.

Traffic between central office and branch exchange switchboard

Referring now more particularly to the operation of the apparatus illustrated in Figs. 3 to 6, inclusive, if a call routed over one of the central office subscribers' lines, such, for example, as the line 11, to an operator's position in the central office 10 is to be extended to a substation line accessible to the branch exchange switchboard, the central office operator handling the call may seize the trunk 12 and, by operation of the ringing key embodied in her cord circuit, project ringing current over this trunk for the purpose of energizing an alternating current relay bridged across the conductor of this line and included in the trunk circuit 13. The resulting operation of this alternating current relay causes the energization of the call lamp 665 individual to the trunk 12. The branch exchange operator, upon observing the lighted condition of this lamp, may answer the call by inserting the plug 661 in the jack 14. In response to this operation, a talking circuit is completed between the calling subscriber's substation and the branch exchange operator's head set, whereby the operator may converse with the calling subscriber and obtain the identity of the desired branch exchange substation. When the plug 661 is inserted in the jack 14, ground potential is impressed upon the ring contact of the jack 14 to cause the energization and operation of one of the relays included in the trunk circuit apparatus 13. The resulting operation of this relay causes the deenergization of the call lamp 665 in the usual manner. When the plug 661 is inserted in the jack 14, a direct current bridge is also established between the tip and sleeve contacts of this jack, thereby to cause the operation of a supervisory relay embodied in the cord circuit in use by the operator handling the call in the central office 10. Assuming that the substation B is desired by the calling central office subscriber, the branch exchange operator may extend the connection to the desired substation by inserting the call plug 662 in the jack 17 and operating the ringing key of the cord circuit 660 to cause ringing current to

be projected over the line 15 and through the windings of the ringer conventionally provided at the substation B. When the call is answered at the called substation, the branch exchange operator may retire from the connection and rely upon the supervisory lamps embodied in the cord circuit 660 to indicate when the connection is ready to be released. When either of the two lamps individual to the calling and called ends of the connection is illuminated, indicating that the connection has been released at one end thereof, the branch exchange operator may clear out the connection. For example, if the called party at the substation B hangs up prior to the release of the connection at the calling end thereof of the supervisory lamp of the cord circuit 660 individual to the called end of the connection is energized to indicate to the branch exchange operator that the connection is ready to be released. The operator may now clear out the connection by withdrawing the plugs 661 and 662 from the jacks 14 and 17, respectively. In response to this operation, the trunk circuit 13 and the line circuit 16 are restored to normal in the usual manner and the bridge circuit established across the conductors of the trunk line 12 is opened to cause the energization of the disconnect lamp associated with the trunk line 12 and embodied in the cord circuit in use at the operator's position in the central office 10. Upon observing the lighted condition of this lamp, the operator handling the call at the central office may clear out the connection in the usual manner.

In the event the call is cleared out at the substation of the calling central office subscriber prior to its release at the substation B, the operator handling the call in the central office 10 receives the first disconnect signal and proceeds to clear out the connection at her position. In response to this operation a disconnect signal is transmitted over the trunk 12 to the cord circuit 660 to cause the energization of the supervisory lamp in the cord circuit 660 which is individual to the calling end of the connection. Energization of this lamp serves to inform the branch exchange operator that the connection has been released at the calling end thereof and may be cleared out at her switchboard. To clear out the connection, the operator withdraws the plugs 661 and 662 from the jacks 14 and 17, respectively, whereby the trunk circuit 13 and the line circuit 16 are restored to normal in the usual manner.

The trunk 12 and the other similar trunks may also be used in routing calls from the branch exchange switchboard to the subscribers' lines terminating at the central office 10. For example, if a call is initiated at the substation B through removal of the receiver provided at this substation from its supporting hook or cradle, the associated hook or cradle switch operates to establish a direct current path between the conductors of the line 15. As a consequence, certain of the relays embodied in the line circuit 16 are operated to complete a circuit for energizing the call lamp 666 individual to the line 15. The branch exchange operator, upon observing the lighted condition of this lamp, may answer the call by inserting the plug 661 in the jack 17. In response to this operation a talking circuit is established between the operator's telephone set and the sub-set in use at the substation B. In addition, ground potential is impressed upon the ring contact of the jack 17 to complete a circuit for energizing the signal lamp cut-off relay conventionally embodied in the line circuit 16.

The resulting operation of this relay causes the deenergization of the call lamp 666. Upon ascertaining that a central office call has been initiated at the substation B, the P. B. X. operator may forward the connection to an operator's position in the central office 10 by inserting the plug 662 in the jack 14 and operating the ringing key embodied in the cord circuit 660 to project ringing current over the trunk line 12. The resulting operation of the signal device or devices individual to this trunk line and provided at the operator's switchboard in the central office 10 serves to inform one or more of the central office operators that a call is present on the trunk line 12 which should be answered. Upon answering the call the central office operator handling the call may converse with the party at the substation B and ascertain the substation desired by the calling party, following which may set up the desired connection in the manner conventionally followed in manual office practice. After the connection has been established, the supervision and release thereof are exactly the same as set forth above with reference to a call routed from a central office subscriber's substation to one of the branch exchange telephone stations.

Central office call to order operator's position

Each of the order operators, when on duty, maintains her telephone set connected to the substation circuit apparatus provided at her position. For example, when an operator is on duty at the order operator's position 21 the terminals of the multiple plug 412' and terminating the cords respectively extending to the transmitter 411 and the receiver 412, are maintained inserted in the jacks 413 and 414, respectively, so that the transmitter 411 is bridged across one winding of the induction coil 415 in series with a coupling condenser and the receiver 412 is bridged across a portion of the other induction coil winding in series with another coupling condenser. With the transmitter 411 connected to the terminals of the jack 413, a circuit extending through the plug and jack contacts and the transmitter 411 is completed for energizing the relay R430 and for supplying energizing current to the transmitter. With the relay R430 in its operated position, a battery marking path is completed, at RA431, for identifying the operator's position 21 as idle in the bank contacts of all of the position finders having access thereto. As explained more in detail hereinafter when the position is occupied with a call this idle marking is removed and a busy ground marking is substituted therefor. Thus, under normal conditions incoming order trunk calls are being handled, certain of the order operators' positions are marked as idle and others are marked as busy in the bank contacts of the position finders. With the relay R430 operated, a circuit extending through RA433 is completed for energizing the position lamp 425 individual to the order operator's position 21 and located at the supervisory operator's position 32, thus indicating to the supervisory operator that the order operator's position 21 is attended.

Assuming that certain of the order operators' positions are conditioned to receive incoming calls, and further that the trunk line 18 is seized at the central office and ringing current is projected thereover, the relay R300 is energized by the ringing current traversing its winding, the resistor 315 and the condenser 317 in series,

Upon operating, the relay R300 completes, at RA301, a circuit for energizing the relay R310, this circuit extending from ground by way of RA301, RA344, RA321 and the winding of R310 to battery. At RA302, the relay R300 prepares a circuit, now open at RA341, for energizing the upper winding of R320. At RA303, the relay R300 prepares a holding circuit for the relay R330. The relay R310 operates after an interval to open, at RA314, the prepared operating circuit for R320; to prepare at RA313, a test circuit including the lower winding of R350; and to complete, at RA312, a circuit extending through RA353 and over C377 for energizing the magnet 409 of the position finder switch 400. At RA313, the relay R310 also completes a priming circuit for the relay R350, this circuit extending through the resistor 358 and the upper winding of R350 to battery. The resistance of this priming circuit is such that R350 does not operate when it is completed. At RA311, the relay R310 connects the winding of the relay R300 directly across the line conductors of the trunk line 18, thereby to cause the operation of an answer lamp embodied in the cord circuit being used by the calling operator in the central office 10 and to establish a loop circuit including the central exchange battery over which the line relay R300 is held energized.

Due to the circuit interrupting action of the armature 410 carried by the magnet 409, the position finder switch 400 operates buzzer fashion so that the wipers thereof are advanced step by step until the contacts corresponding to the first idle order operator's position are selected. During this operation of the switch 400 the lower winding of the relay R350 is short circuited so long as the test wiper 407 is passing over contacts corresponding to busy order operators' positions. Assuming that the order operator's position 21 is the first idle position available, operation of the switch 400 is arrested when the wipers of this switch are advanced to the position corresponding to this order operator's position. More specifically, when the test wiper 407 engages the associated test contact individual to the position 21, the above-mentioned test circuit is completed, this circuit extending from ground by way of RA313, the lower winding of R350, C378, the wiper 407, RA431 and the winding of R440 to battery. When its lower winding is energized over this circuit the relay R350 first operates to complete, at the X contacts associated with RA354, an obvious path for short-circuiting the resistor 358, whereby its upper winding is fully energized. Following this operation, the relay R350 fully operates to open, at RA353, the above-traced operating circuit for the magnet 409, thereby to arrest operation of the switch 400 with the wipers of this switch standing on the contacts terminating the conductors extending to the substation apparatus provided at the order operator's position 21. At RA351 and RA352, the relay R350 connects the conductors of the trunk line 18 through the line wipers 405 and 406 of the line switch 400 to the line terminals of the induction coil 451, thus completing a talking circuit between the calling central office subscriber's substation and the telephone set in use by the operator attending the position 21. At RA355, the relay R350 prepares a circuit traced hereinafter for energizing the combined call transfer and trunk release relay R340. At RA356, the relay R350 opens a point in the prepared holding circuit for R330. At

RA357, the relay R350 removes ground potential from the marking wiper 368 of the storage position finder switch 360. With the wipers of the line switch 400 standing on the contacts of this switch corresponding to the order operator's position 21 ground potential as connected through the lower winding of R350 and over C378 to the wiper 407 is impressed upon the test contacts of all of the other position finder switches which correspond to the order operator's position 21, thus identifying this order operator's position as busy in the contacts of the other position finder switches.

As indicated above, the slow-to-operate relay R440 is energized in series with the lower winding of the relay R350 immediately the order operator's position 21 is selected by the position finder switch 400. The relay R440 operates after an interval to complete, at RA442, an obvious circuit for energizing the call signal lamp 423, thereby to indicate to the operator attending the position 21 that an incoming call should be answered. At RA442, the relay R440 also opens one of the multiple paths over which ground potential is normally impressed upon the storage start conductor C483. At RA443, the relay R440 completes an obvious circuit for energizing the busy lamp 424 provided at the supervisory operator's position 32 and individual to the order operator's position 21.

Following operation of the relay R350 to establish a talking circuit between the calling central office subscriber's substation and the operator's position 21, the order operator attending this position may converse with the calling subscriber and give the calling subscriber the information desired. In order to initiate the release of the connection after the conversation is terminated, the operator attending the position 21 momentarily actuates the release key 416 to the off-normal position required to cause engagement of the springs 418. When these contact springs are engaged a circuit is completed for partially energizing the call transfer and trunk release relay R340, this circuit extending from ground by way of the resistor 419, the springs 418, the wiper 408, C379, RA355 and the winding of R340 to battery. When energized over this circuit the relay R340 partially operates to open the closed contacts associated with RA344 without closing the make contacts associated with this armature. As a result, the above-traced operating circuit for the relay R310 is interrupted and this relay restores to open the holding circuit for R350; to open a further point in the operating circuit for the driving magnet 409; and to disconnect the winding of the line relay R300 from across the conductors of the trunk line 18, thereby to cause the energization of a disconnect signal lamp provided in the cord circuit in use in the central office 10 in the usual manner. The relays R300, R350 and R440 now restore. Shortly thereafter and when the call transfer and trunk release key 416 is released and allowed to return to its normal position, the springs 418 are opened to open the circuit for partially energizing the transfer and release relay R340, causing this relay to restore. The relay R440, upon restoring opens, at RA442, the circuit for energizing the call lamp 423; prepares, at RA441, the path for impressing ground potential upon the distributor start conductor C480; completes, at RA442, the multiple path, individual to the position 21, over which ground potential is normally impressed upon the conductor C483; and opens, at RA443, 75

the circuit for energizing the busy lamp 424 provided at the supervisory operator's position 32. Thus, the trunk circuit apparatus 19 is fully restored to normal and the order operator's position 21 is again identified as idle in the bank contacts of the various position finders having access thereto. When the central office operator handling the call observes the lighted condition of the supervisory lamp associated with the called end of the connection, she may clear out the connection at her position in the manner conventionally followed in manual office practice.

If the connection routed over the trunk line 18 to the order operator's position 21 is released at the operator's position in the central office 10 prior to actuation of the transfer and release key 416 in the manner set forth in the preceding paragraph, the relay R300 restores to open the operating circuit for the relay R310. The relay R310, upon restoring, causes the release of the relays R350 and R440 in the manner previously explained. Thus, in the case where the connection is cleared out at the operator's position in the central office 10, the trunk circuit 19 and the operator's position circuit are fully released without any operation on the part of the order operator attending the position 21.

Transfer of order trunk call to branch exchange switchboard

30 In the event the order operator attending the position 21 finds it necessary to converse with a party located at one of the branch exchange substations in order to obtain the information desired by the calling subscriber, or to connect the calling subscriber directly to one of the branch exchange substations, she may route the call to the branch exchange switchboard by operating the transfer and release key 416 to the off-normal position required to cause engagement of the contact springs 417. In response to this operation the relay R340 is energized over a circuit from which the resistor 419 is excluded and, accordingly, is caused fully to operate. While assuming its fully operated position, the relay R340 completes, at RA344, an obvious holding circuit for the relay R310; at the same time opening the initially completed operating circuit for the latter relay. At RA342 and RA343, the relay R340 opens the established talking circuit extending between the calling subscriber's substation and the substation equipment provided at the order operator's position 21. At RA341, the relay R340 completes a circuit for energizing the signal lamp 653 provided at the branch exchange switchboard, this circuit extending from ground by way of RA341, C345, the jack springs 654 and the filament of the lamp 653 to battery. The energization of the lamp 653 serves to inform the branch exchange operator that a call is present on the transfer trunk 22 which should be answered. To answer the call the branch exchange operator may insert the answer plug 661 of the cord circuit 660 in the jack 23, thereby to complete a talking circuit between her telephone set and the telephone set in use by the operator attending the order operator's position 21. When the plug 661 is inserted in the jack 23, the springs 654 are disengaged in an obvious manner to open the above-traced circuit for energizing the signal lamp 653. Following the operations just described the operator attending the order operator's position 21 may converse with the branch exchange operator and direct the latter operator to extend the connection to the desired line.

Assuming, for example, that the substation B is desired by the order operator, the branch exchange operator may route the connection to this substation by inserting the call plug 662 in the jack 17 and operating the ringing key provided in the cord circuit 660 to cause ringing current to be projected over the line 15 for the purpose of energizing the ringer or signal device provided at the substation B. When the call is answered at the substation B, the desired talking circuit may be established through the operator's cord circuit 660 between this substation and the substation apparatus provided at the order operator's position 21. With the apparatus in this condition the operator attending the position 21 may converse with the answering party at the substation B to obtain the desired information, and during the course of the conversation the calling central office subscriber is excluded from the connection. If the operator attending the position 21 desires, she may establish a three-way talking circuit between her substation, the central office subscriber substation and the substation B. To this end, the transfer and release key 416 is restored to its normal position. In response to this operation the transfer and release relay R340 is released to open the completed holding circuit for the relay R310 and to recomplete the operating circuit for this relay. At RA342 and RA343, the relay R340 connects the conductors of the order trunk 18 to the talking conductors of the transfer trunk 22, thereby to establish a talking circuit between her station, the calling central office substation and the substation B. Upon restoring, the relay R340 also opens, at RA341, a further point in the previously traced circuit for energizing the signal lamp 653. After the connection is established between the substation B and the substation of the calling central office subscriber in the manner just explained the operator attending the order operator's position 21 may return from the connection and release the trunk circuit 19 and the position circuit individual to the position 21 by operating the transfer and release key 416 to the position required to cause engagement of the contact springs 418. The manner in which the trunk circuit apparatus 19 and the order operator's position circuit are released in response to operation of the transfer and release key 416 is exactly the same as described previously. Following the release of this apparatus, supervision of the call as extended through the operator's cord circuit 660 to the substation B is under the control of the branch exchange operator, the supervisory lamps provided in the cord circuit 660 being utilized to indicate when the connection is no longer desired. In this regard it is pointed out that an auxiliary direct current bridge is established in the operator's cord circuit 660 between the line conductors of the order trunk 18 when the answer plug 661 is inserted in the jack 23 and the transfer and release relay R340 is restored to normal. Thus, energization of the disconnect lamp associated with the trunk 18 and provided in the cord circuit in use in the central office 10 is under the control of the branch exchange operator. More particularly, if the branch exchange operator receives a disconnect signal caused by release of the connection at the substation B, she may clear out the connection by withdrawing the call and answer plugs 662 and 661, respectively, from the jacks 17 and 23, respectively. In response to this operation the established direct current bridge across the

conductors of the trunk 18 is interrupted causing the energization of the disconnect lamp provided in the cord circuit in use in the central office 10. The central office operator may then clear out the connection in the usual manner. If the central office subscriber is the first to abandon the connection, the central office operator may clear out the connection in the usual manner and in so doing opens the loop circuit extending by way of the trunk 18 and the transfer trunk 22 to the operator's cord circuit 660, thus causing the energization of the disconnect lamp provided in this cord circuit. As a consequence, the branch exchange operator is informed that the connection is ready for release and may clear out the connection by withdrawing the plugs 662 and 661 from the jacks 17 and 23, respectively.

Call from order operator's position to branch exchange switchboard

If for any reason the operator attending the order operator's position 21 finds it necessary to obtain information from one of the clerks or employees normally attending one of the branch exchange substations, she may cause a connection to be routed to the branch exchange switchboard by operating the call key 420 to its off-normal position. In response to this operation the contact springs 435 are engaged to prepare a circuit, traced hereinafter, for energizing the relay R440; the contact springs 433 and 434 are disengaged to open the associated multiple path over which ground potential is normally impressed upon the conductor C483; and the springs 433 and 432 are engaged to complete a circuit for energizing the distributor start relay R610. This circuit extends from ground by way of the springs 433 and 432, RA441, C480, the winding of R610, RA613, the armature 652 and the winding of the magnet 651 to battery. Due to the relatively high resistance of the winding of the relay R610, the magnet 651 is insufficiently energized to operate when this circuit is completed. The relay R610, however, operates after an interval to prepare, at RA612, a circuit for energizing the winding of R620, the lower winding of R630 and the winding of R440 in series. At RA613, the relay R610 opens the path normally short-circuiting the resistor 615, thereby to insert further resistance in the above-traced circuit serially including its own winding and the winding of the magnet 651. At RA614, the relay R610 opens an alternative circuit for energizing the magnet 651 and completes an obvious circuit for energizing the slow-to-release relay R600. The relay R600, upon operating, prepares the alternative circuit for energizing the magnet 651. Assuming that the wipers of the distributor switch 640 are positioned in engagement with the contacts corresponding to the trunk 26 and associated position finder 29, the relay R610 completes, at RA611, a circuit for energizing the operating magnet 457 of the finder switch 450, this circuit extending from ground by way of RA611, RA631, the wiper 646, C476 and the winding of the magnet 457 to battery. The magnet 457, upon operating, completes, at its armature 458, a circuit extending by way of C477 and the wiper 647 for energizing the upper winding of R630. The relay R630 now operates to open, at RA631, the operating circuit for the magnet 457, causing this magnet to release and advance the wipers 454 to 456 inclusive, one step. At its armature 458, the magnet 457 opens the circuit for energizing the relay R630. Accordingly, the

relay R630 restores to recomplete the circuit for energizing the magnet 457. The interrelated operation of the magnet 457 and the relay R630 continues until the wipers 454 to 456, inclusive, are advanced into engagement with the contacts terminating the conductor individual to the order operator's position 21. When the wipers of the switch 450 are advanced to this position, the above-mentioned circuit is completed for energizing the three relays R440, R620 and R630 in series, this circuit extending from ground by way of RA612, the winding of R620, the lower winding of R630, the wiper 648, C472, the wiper 456, the contact springs 435 and the winding of R440 to battery. When this circuit is completed, ground potential, as extended through the winding of R620 and the lower winding of R630 to the left winding terminal of the relay R440, is impressed upon the contact associated with the wiper 401 which corresponds to the order operator's position 21. This contact is multiplied to the corresponding contacts of each of the other position finders having access to the order operator's position 21 so that all of these contacts are effectively grounded, thereby to busy the order operator's position 21 to the various position finders. When the above-traced circuit is completed the relay R630 is held operated independently of the magnet 457 so that the operating circuit for this magnet cannot be recompleted and operation of the finder switch 450 is arrested. The relay R620 upon operating completes, at RA621, a circuit for energizing the lower winding of R440, this circuit extending from ground by way of RA621, the wiper 650, C473 and the lower winding of R440 to battery. Upon operating the relay R440 completes a holding circuit for itself and the relay R440, this circuit extending from ground by way of the upper winding of A460, RA463, the wiper 456, the contact springs 435 and the winding of R440 to battery. The ground potential, as extended through the upper winding of R440 to the left terminal of R440 also serves to mark the operator's position 21 as busy in the bank contacts of the various position finders individual to the order trunks. At its armatures RA461 and RA462, the relay R460 connects the talking conductors of the trunk 26 to the substation apparatus provided at the order operator's position 21. At RA463, the relay R460 completes a circuit for energizing the call lamp 663 individual to the trunk line 26, this circuit extending from ground by way of the jack springs 664, C478, RA465, C479 and the filament of the lamp 663 to battery. The resulting illumination of this lamp serves to inform the branch exchange operator that an incoming call on the trunk 26 should be answered. At RA464 and its associated resting contact the relay R460 opens one of the paths over which ground potential is normally impressed upon the all-trunks-busy conductor C475. At RA464 and its associated working contact the relay R460 completes a path including C474 for impressing ground potential upon the test contact associated with the wiper 649 which corresponds to the finder switch 450, thus identifying the trunk 26 as busy in the bank contacts of the distributor switch and short circuiting the relay R610.

The relay R440 operates shortly following the operation of the three relays R620, R630 and R460 and, upon operating, opens, at RA442, one of the multiple paths over which ground potential is normally impressed upon the conductor C483. At RA443 the relay R440 completes the

10 circuit for energizing the signal lamp 424 provided at the supervisory operator's position 32, thus indicating to the supervisory operator that the order operator's position 21 is busy. At RA441 the relay R440 disconnects the distributor start conductor C480 from ground, thereby to open the initially completed operating circuit for the distributor start relay R610. As indicated above, the relay R610 is short-circuited over the conductor C474 in response to operation of the relay R460. When thus short-circuited, the relay R610 restores to open a further point in the operating circuit for the motor magnet 457, and to interrupt the operating and holding circuits for the relays R620 and R630, causing these two relays to restore. At RA614, the relay R610 opens the operating circuit for the slow-to-release relay R600 and completes a circuit extending through RA601 for energizing the magnet 651 of the distributor switch 640 until the relay R600 releases. When energized over this circuit the magnet 651 attracts its armature 652 to open its test circuit. At RA613, the relay R610, upon restoring, short circuits the resistor 615, thereby further to prepare the test circuit for the distributor switch driving magnet 651. When the relay R600 releases, the magnet 651 is deenergized and in cooperation with the associated ratchet and pawl mechanism steps the wipers 646 to 650, inclusive, into engagement with the contacts corresponding to the next position finder switch. In the event the wipers 646 to 650 inclusive, are now standing on a set of contacts corresponding to an idle position finder switch, no further operation of the distributor switch 640 occurs. On the other hand, if the contacts engaged by these wipers terminate conductors extending to a busy position finder switch, ground potential is connected through the associated test contact to the wiper 649 so that the magnet 651 is again energized and operates to advance the wipers a second step. Due to the circuit interrupting action of the armature 652 the stepping operation of the switch 640 continues until the wiper 649 is advanced into engagement with a test contact from which ground is disconnected; that is, a test contact corresponding to an idle one of the position finder switches. When this occurs the stepping operation of the distributor switch 640 is arrested, the wipers 646 to 650, inclusive, being left standing in engagement with the contacts corresponding to the selected idle position finder switch. If all of the finder switches are busy at the time operation of the distributor switch 640 is initiated, the stepping operation of this switch continues until the wiper 649 is driven into engagement with the last contact of the associated contact set. When an all-busy condition of the position finders and associated trunk prevails, all of the relays corresponding to and including the relay R460 individual to the position finder 29 and trunk 26 are operated and the conductor C475 is disconnected from ground. Accordingly, when the wiper 649 is operated to engage the contact terminating the conductor C475 no further circuit is available for energizing the magnet 651 and operation of the distributor switch 640 is arrested. When thereafter one of the position finders is released to cause the restoration of the relay embodied therein which corresponds to the relay R460 of the position finder 29, ground potential is again impressed upon the conductor C475 to again initiate the stepping operation of the distributor switch

640, this stepping operation continuing until the wipers 646 to 650, inclusive, are driven to the position corresponding to the position finder which has been released. When the idle position finder is found, the wiper 649 is disconnected from ground and the magnet 651 is deenergized. Following the hunting operation of the distributor switch 640, as described above, the distributor 30 is fully released and is conditioned to respond to the initiation of a call at another of the order operators' positions.

When the branch exchange operator observes the illuminated condition of the lamp 663 indicating that a call is present on the trunk 26 she may answer the call by inserting the answer plug 661 in the jack 28. In response to this operation a talking circuit is completed between the cord circuit 660 and the telephone set in use at the order operator's position 21. In addition, the jack springs 664 are disengaged to interrupt the 15 previously traced circuit energizing the call lamp 663. The branch exchange operator, after conversing with the order operator attending the position 21, may extend the connection to the desired branch exchange substation by inserting 20 the plug 662 in the jack terminating the line extending to this substation and actuating the ringing key embodied in the cord circuit 660 to project ringing current over the line thus selected. For example, if the substation B is desired by 25 the order operator attending the position 21 the branch exchange operator may insert the calling plug 662 in the jack 17 and actuate her ringing key, thereby to cause ringing current to be transmitted over the line 15 and through the windings 30 of the ringer provided at the substation B. After the call is answered at the substation B the branch exchange operator may retire from the connection leaving the desired talking circuit 35 established between this substation and the order operator's position 21.

In order to release the connection thus established to the substation B the order operator attending the position 21 restores the call key 420 to its normal position. In response to this operation the contact springs 435 are disengaged to open the circuit including the winding of R440 and the upper winding of R460, causing these two relays to restore. When the call key 420 is restored to normal the springs 432 and 433 are also disengaged to open a further point in the path for impressing ground potential upon the distributor start conductor C480. In addition, the contact spring 433 is moved into engagement with the contact spring 434 to reprepare the 40 multiple path, individual to the order operator's position 21, over which ground potential is normally impressed upon the conductor C483. The relay R440 releasing, reprepares, at RA441, the path for impressing ground potential upon the distributor start conductor C480 and recompletes, at RA442, the above-mentioned path, individual to the order operator's position 21, for impressing ground potential upon the conductor C483. At RA443 the relay R440 opens the circuit for energizing the busy lamp 424, individual to the order operator's position 21 and located at the supervisory operator's position 32, thus indicating to the supervisory operator that the order operator's position 21 is again idle. The relay R460, upon restoring, opens, at RA463, a further point in the above-traced holding circuit for itself and the relay R440. At RA461 and RA462 the relay R460 opens two points in the completed loop circuit including the upper winding of the induc-

tion coil 451 and extending by way of the trunk 26 to the operator's cord circuit 660. The interruption of this loop circuit causes the energization of the disconnect signal lamp provided in the operator's cord circuit 660, thus indicating to the branch exchange operator that the connection has been cleared out at the calling operator's position and may be released. At RA464, the relay R460 disconnects the marking lead C474 individual to the position finder 29 from ground, thereby to mark this finder as idle in the bank contacts of the distributor switch 640. At RA464 and its associated resting contact, the relay R460 completes the multiple path, individual to the position finder 29, for impressing ground potential upon the all-trunks-busy conductor C475. At RA465, the relay R460 opens a further point in the previously traced circuit for energizing the call lamp 663 individual to the trunk line 26. The branch exchange operator, upon observing the lighted condition of the disconnect lamp included in the cord circuit 660, may clear out the connection by withdrawing the plugs 661 and 662 from the jacks 28 and 17, respectively. Thus, the apparatus utilized in setting up the connection is fully released.

Call storage

As indicated previously, the call storage circuit 31 in conjunction with the call storage position finder switches individual to the order trunk circuits, are provided for the purpose of storing calls to the order operators' positions when all of these 35 positions are busy and for routing the stored calls to the order operators' positions as the operators' positions are released in the order in which the calls are stored. More particularly, when all of the order operators' positions are occupied with calls or portions thereof are occupied with 40 calls and the others are not attended, the multiple paths individual to the various positions and over which ground potential is normally maintained upon the common conductor C483 are all interrupted. As a result, the relay R540 45 is energized over a circuit extending from ground through the winding of this relay and by way of C483, the contacts of the no-storage key 422 and the resistor 484 to battery. When energized over this circuit the relay R540 operates to disconnect the wiper 515 of the switch 510 from ground and to complete an obvious path for applying ground potential to the conductor C371. This conductor is commonly included in the operating circuits, traced hereinafter, for the relay 50 R320 and the corresponding relays individually provided in the trunk circuits respectively terminating the other order trunks extending to the central office 10. The relay R540 is, at this time, the only operated relay in the call storage circuit 31. Further, the call storage distributor switch 500 may at this time occupy any one of its twenty-four operating positions, while the wipers of the call release switch 510 may occupy any one of a number of positions behind the 55 positions occupied by the wipers of the switch 500.

With the apparatus in this condition if a call is routed from the central office 10 over the order trunk 18 to cause the operation of the relay R300 in the manner previously explained, the winding of the relay R310 and the upper winding of the relay R320 are energized in parallel. The circuit for energizing the upper winding of the relay R320 extends from ground by way of RA541, the common conductor C371, RA332, RA302, RA314 and the upper winding of

R320 to battery. Due to the slow-to-operate characteristic of the relay R318 and the relatively fast operating characteristic of the relay R320, the last-mentioned relay operates to interrupt, at RA321, the completed operating circuit for the relay R310 before the latter relay can operate. Since the relay R310 is prevented from operating, operation of the position finder switch 400 is not initiated in response to seizure of the associated trunk line 18. Further, with the relay R310 in its restored position the winding of the relay R300 is not bridged across the conductors of the trunk line 18 to give the central office operator answering supervision in the manner previously explained. Also, the operating circuit for the relay R320 is not opened and no circuit is provided for energizing either of the windings of the stop relay R350. The relay R320 upon operating completes, at RA321', an obvious path for bridging the winding of the relay R300 across the conductors of the trunk 18 in series with the resistor 315, whereby the relay R300 is held operated through energization from the central office battery. The resistance value of the resistor 315 is such that the answer relay of the record circuit in use in the central office is not sufficiently energized to operate when this path is completed. At RA323 and its associated resting contact, the relay R320 opens the path normally short-circuiting its lower winding. At RA322 and RA323, the relay R320 completes a locking circuit for itself, which circuit extends from ground by way of RA334, RA322, the lower winding of R320 and the resistor 316 to battery. At RA324, the relay R320 completes a circuit extending by way of C380 for energizing the trunk call storage lamp 426 individual to the trunk 18, thereby indicating to the supervisory operator that a call present on the trunk line 18 has been placed in storage. At RA325, the relay R320 prepares a circuit, traced hereinafter, for energizing the stop relay R330. At RA326, the relay R320 completes a circuit for energizing the relay R520, this circuit extending from ground by way of RA326, C373, the winding of R520 and RA573 to battery. At RA327 and its associated resting contact, the relay R320 opens a point in the release or homing circuit for the operating magnet 369 of the call storage finder switch 368. At RA327 and its associated working contact, the relay R320 completes a circuit for energizing the magnet 369, this circuit extending from ground by way of the restored armature RA532, C374, RA327, RA337, the armature 370 and the winding of the magnet 369 to battery. Due to the circuit interrupting action of the armature 370, the magnet 369 operates buzzer fashion when the circuit just traced is completed and, in cooperation with its associated ratchet and pawl mechanism, advances the wipers 365 to 368, inclusive, until these wipers find the position marked in the contacts of the call storage position distributor switch 500. Assuming, for example, that the wipers of the switch 500 stand in engagement with their respective associated fourth contacts, the wipers of the switch 360 are advanced three steps, at which time they also engage their respective associated fourth contacts. When the wiper 367 engages its associated fourth contact, a circuit is completed for energizing the lower winding of R330 in series with the relay R560, this circuit extending from ground by way of RA325, the lower winding of R330, the switch wipers 367 and 506 and their respective associated fourth contacts, the armature 508 and 75

the winding of R560 to battery. Immediately this circuit is completed, the relay R330 operates to open, at RA331, the operating circuit for the magnet 369, whereby operation of the switch 368 is arrested with the wipers of this switch standing in engagement with their associated fourth contacts. At RA336, the relay R330 completes an obvious locking circuit for itself. At RA331, the relay R330 completes an obvious multiple path including the resistor 315 for bridging the winding of the relay R300 across the conductors of the trunk line 18. At RA332, the relay R330 opens a point in the above-traced operating circuit for the relay R320 and connects multiple ground to the common conductor 311, thereby to insure the storing of a later initiated order trunk call initiated substantially simultaneously with the release of an order operator's position. At RA333 and RA334, the relay R330 transfers locking ground for the lower winding of the relay R320 to the operated make springs associated with RA301. At RA335, the relay R330 prepares a path, traced hereinafter, for short-circuiting the lower winding of the relay R320 when an order operator's position becomes available.

When the relay R560 is energized in series with the lower winding of R330 it operates after an interval to complete, at RA561, a circuit extending by way of RA531 for energizing the operating magnet 507 of the switch 500. When thus energized, the magnet 507 attracts its associated armature 508 to open the circuit through the winding of R560 and the lower winding of R530, thereby to cause the release of the relay R560. This relay releasing opens the circuit for energizing the magnet 507, whereby this magnet in cooperation with its associated ratchet and pawl mechanism steps the wipers 504 to 506, inclusive, of the switch 500 to the next storage position. Since this next storage position is not occupied with a stored call, the wiper 506 engages an open circuited contact and no further operation of the relay R560 and the magnet 507 occurs. The purpose of stepping the wipers of the switch 500 one step in the manner just explained is to mark the next storage position of this switch as the position to be assigned to the next call routed over one of the order trunks at a time when all of the order operators' positions are busy.

As indicated above, the relay R520 is energized and operates in response to operation of the relay R320, immediately the call is initiated on the trunk line 18. The relay R520 operating, completes, at RA521, an obvious circuit for energizing the operating magnet 517 of the switch 510. This magnet attracts its armature 518 to complete an obvious circuit for energizing the slow-to-release relay R570. The relay R570 operating prepares, at RA571, a holding circuit for itself; prepares, at RA572, a circuit for energizing the lower winding of R550; and opens, at RA573, the established operating circuit for the relay R520. The relay R520 releasing opens the established circuit for energizing the magnet 517. The magnet releasing advances the wipers of the switch 510 one step and retracts its associated armature 518 to interrupt the operating circuit for the relay R570. The relay R570 releasing recompletes the operating circuit for the relay R520 which reoperates to again complete the operating circuit for the magnet 517. The interrelated operation of the two relays R520 and R570 and the magnet 517 continues until the wipers of the switch 510 are positioned on the contacts marked by the set-

ting of the call storage finder switch 368. In the case assumed the wipers of the switch 368 are rapidly advanced to engage their respective associated fourth contacts in response to operation of the relay R328. Accordingly, the wipers of the switch 518 are advanced to engage their respective associated fourth contacts. When the wiper 516 engages its associated fourth contact, the above-mentioned circuit is completed for energizing the lower winding of R558, this circuit extending from ground at RA357 by way of the wipers 368 and 516 and their respective associated fourth contacts, RA512 and the lower winding of R558 to battery. This circuit is completed while the relay R570 occupies its operated position and, accordingly, when the relay R558 operates the above-mentioned locking circuit for R570 is established, this circuit extending from ground by way of RA551, RA571 and the winding of R570 to battery. Thus, the two relays R558 and R570 are locked up under the control of the relay R358 to prevent any further operation of the relay R528 and the magnet 517. At this point it is noted that in the trunk circuit 19, the relays R388, R328 and R338 are operated, while 20 in the call storage circuit 31 the relays R540, R558 and R570 are operated. With the apparatus in this condition no further operation thereof occurs until one of the order operators' positions is released, the stored call on the order trunk 18 is abandoned, or a second call is routed over one of the order trunks.

If the call present on the order trunk 18 is abandoned at the calling central office subscriber's substation prior to the release of one of the order operators' positions and the established connection to the line 18 is cleared out at the operator's switchboard in the central exchange 18, the relay R388 restores. Upon restoring, this relay, at its armature RA381, opens the established locking circuit for the relay R328 and applies multiple ground to the all-trunks-busy conductor C312. At RA382, the relay R388 opens a point in the previously traced operating circuit for the relay R328. At RA383, the relay R388 interrupts the locking circuit for the relay R328. Thus, the two relays R328 and R338 are caused to release. The relay R328 releasing opens, at RA324, the circuit for energizing the trunk call storage lamp 426; reprepares, at RA321, the operating circuit for the relay R310; opens, at RA325, a further point in the operating circuit for the relay R338; opens, at RA326, the path individual to the trunk circuit 19 over which ground potential is impressed on the conductor C313; and, at RA327, opens a point in the initially completed operating circuit for the magnet 369 and prepares an alternative circuit for energizing this magnet. The relay R338 releasing opens, at RA331, the path bridging the winding of the relay R388 across the conductors of the trunk 18; disconnects, at RA332, multiple ground from the common conductor C371; reprepares, at RA332, the operating circuit for the relay R328; opens, at RA333 and RA334, an additional point in the holding circuit for the relay R328; opens, at RA335, the prepared path for short-circuiting the lower winding of R328; opens, at RA336, a further point in its own locking circuit; and completes, at RA337, the above-mentioned alternative circuit for energizing the magnet 369. This circuit extends from ground by way of the wiper 365, the multiplied contacts numbered from 2 to 25, inclusive, of the contact set 361, RA327, RA337, the armature 370 and the winding of the 75

magnet 369 to battery. Due to the circuit interrupting action of the armature 370, the wipers of the switch 368 are rapidly advanced step by step to their respective home positions at which time the wiper 365 engages its associated first contact. Since this contact is not connected to ground, the circuit for energizing the magnet 369 is interrupted and operation of the switch 368 is arrested. Thus, the wipers of the switch 368 are left standing in their respective home positions. During this stepping operation of the switch 368 and when the wiper 368 is disengaged from its associated fourth contact, the previously traced operating circuit for the relay R558 is interrupted causing this relay to restore and open the locking circuit for the relay R570. As a result, the relay R570 restores after an interval to re-prepare the operating circuit for the relay R528. Under the circumstances assumed, wherein only the call originating on the order trunk 18 has been stored, ground potential is not present on the common conductor C373 when the relay R570 restores. Accordingly, the relay R528 is not re-operated to initiate operation of the switch 518. Following the operations just described, the order trunk circuit 19 is fully restored to normal and all of the relays in the call storage circuit, with the exception of the relay R540, are released.

If the order operator's position 21 is released 30 while the call originating on the order trunk 18 is in storage, the relay R440 embodied in the apparatus provided at this position is released and the position is marked as idle in the bank contacts of the position finders having access thereto. The relay R440 releasing completes, at RA442, its associated path for impressing ground potential upon the common conductor C483, thereby to short-circuit the winding of the relay R540. The relay R540 releasing disconnects ground from the common conductor C371 and completes, at RA541, the previously mentioned path for short-circuiting the lower winding of R328, this path extending from ground by way of RA541, the wipers 515 and 366 and their respective associated fourth contacts, RA335, the lower winding of R328, RA323, RA322, RA334, RA333 and RA301 back to ground. When thus deenergized, the relay R328 releases to short-circuit its lower winding and open the short-circuiting path just traced. At RA324, the relay R328 opens the previously traced circuit for energizing the trunk call storage lamp 426, thereby indicating to the supervisory operator attending the position 32 that the call present on the order trunk 18 has been released from storage. At RA325, the relay R328 opens a further point in the previously traced circuit for energizing the lower winding of R330 and the winding of R560 in series. At RA326, the relay R328 opens the associated path for impressing ground potential on the conductor C373. At RA327, the relay R328 opens a further point in the initially completed operating circuit for the magnet 369 and prepares the above-traced alternative circuit for energizing this magnet. At RA321, the relay R328 completes the previously traced operating circuit for the relay R310. The relay R310 operating bridges the winding of the relay R300 directly across the conductors of the trunk 18, thereby to cause the operation 60 of the answer relay provided in the operator's cord circuit in use in the central office 10. The relay R310 operating, also initiates operation of the position finder 400 to find the order operator's position 21 which has been released, all in the manner previously described. At RA314, the re-

lay R310 opens a point in the previously traced operating circuit for the relay R320. When the wipers of the position finder 400 are positioned on the contacts corresponding to the operator's position 21, the relays R350 and R440 are energized and operate in the manner hereinbefore described. The relay R350, in operating performs the functions previously described, and, in addition, opens, at RA356, the established locking circuit for the relay R330 permitting the latter relay to release. At RA357, this relay R350 opens the previously traced operating circuit for the relay R550, thereby to cause the sequential release of the relays R550 and R570 in the order named. Thus, the apparatus provided in the call storage circuit 31 is fully restored to normal. It is to be noted that if none of the other order operators' positions have been released substantially simultaneously with the release of the order operator's position 21, the relay R440 in operating opens the only completed multiple path for impressing ground potential upon the common conductor C483. As a result, the operating circuit for the relay R540 is reestablished and this relay operates. With the relay R540 operated, further calls routed over the order trunks to the order operators' positions are stored until such time as a corresponding number of the order operators' positions are released.

The relay R330 releasing opens, at RA333, RA334 and RA332, additional points in the previously traced operating, holding and release circuits for the relay R320; opens, at RA336, a further point in its own locking circuit; opens, at RA331, the initially completed path for bridging the winding of the relay R300 across the conductors of the trunk 18; disconnects, at RA332, the conductor 371 from ground; and reprepares, at RA332, the operating circuit for R320. At RA337, the relay R330 completes the previously traced alternative circuit for energizing the magnet 369, causing this magnet, in cooperation with its associated ratchet and pawl mechanism, to advance the wipers 365 to 368, inclusive, step by step until they are moved to their respective home positions. Following the operations just described, the desired connection between the central office subscriber's substation and the order operator's position 21 is fully established. This connection may be routed to the branch exchange switchboard or through this switchboard to one of the branch exchange substations or may be released under the control of the operator attending the position 21, all in the manner previously described.

In the event a plurality of calls intended for the order operators' positions are routed over the order trunks at a time when all of the order operators' positions are busy, these calls are assigned successive storage positions by the switch 500. In this regard it will be recalled from the previous explanation that the wipers of the switch 500 were advanced one step to a new call storage position in response to storage of the call routed over the order trunk 18. More specifically, these wipers were advanced to engage their respective associated fifth contacts. If, with the wipers of the switch 500 standing in this position, a second order trunk call is initiated prior to the release of one of the order operators' positions the trunk circuit apparatus associated with the order trunk in use operates in substantially the manner described above with reference to the order trunk circuit 19, except that the wipers of the call storage finder switch embodied in the

second trunk circuit are operated to engage their respective associated fifth contacts and are left standing in this position. Following such operation of the second call storage finder switch, the wipers of the switch 500 are advanced an additional step and are left standing in engagement with their respective associated sixth contacts. With these wipers in this position a third order trunk call initiated prior to the release of any of the order operators' positions is assigned the sixth storage position under the control of the wipers embodied in the switch 500. It will thus be apparent that order trunk calls initiated at a time when an all-busy condition of the order operators' positions prevails are assigned successive storage positions under the control of the switch 500.

The purpose of the switch 510 and its associated control apparatus is to release the calls from storage in the same order as they are stored. Thus, if in the case considered above a plurality of the trunk calls are stored prior to the release of the order operator's position and the call on the order trunk 18 is the first call stored, the order operator's position 21 is assigned to the use of the order trunk 18. This is true for the reason that the relays R550 and R570 are held locked up under the control of the relay R350 regardless of the number of steps taken by the wipers of the switch 500 following the locking up of these two relays. Under these circumstances, when the relay R350 operates in response to operation of the position finder 400 to seize the order operator's position 21, it opens the established operating circuit for the relay R550 causing the latter relay to release and open the established locking circuit for the relay R570. The relay R570 restores after an interval to recomplete, at RA573, the operating circuit for the relay R520. This latter relay operating completes the circuit for energizing the magnet 517 which magnet, in turn, completes the operating circuit for the relay R570. The relay R570 operating opens the operating circuit for the relay R520 to cause the sequential restoration of the latter relay and the magnet 517, whereby the wipers 514 to 516, inclusive, are advanced to engage their respective associated fifth contacts corresponding to the second stored call. If this call has not been abandoned, ground potential is present upon the fifth contact of the contact set 513 as a consequence of the setting of the call storage finder switch individual to the order trunk over which the second stored call was routed. Accordingly, the relay R550 reoperates to close the locking circuit for the relay R570 and thus prevents further operation of the relay R520 and the magnet 517. The relays R550 and R570 are thus locked up under the control of the relay corresponding to the relay R350 and embodied in the trunk circuit individual to the order trunk over which the second stored call was routed, and remain locked up until a second order operator's position is thereafter released.

In the event the second stored call is abandoned prior to the release of the order operator's position 21 and the resulting operation of the order trunk circuit 19, in the manner set forth above, ground potential is not present upon the contact of the set 513 which corresponds to the second stored call, namely, the fifth contact of this set. Accordingly, a second cycle of operation of the two relays R570 and R520 and the magnet 517 occurs so that the wipers of the switch 510 are advanced to engage their respective associated

sixth contacts. If the stored call corresponding to this position of the switch 510 has also been abandoned the cyclic operation of the two relays R570 and R520 and the magnet 517 again occurs to advance the wipers of the switch 510 into engagement with their respective associated seventh contacts. When the position of the switch 510 corresponding to the next call in storage is found, the relays R550 and R570 are locked operated under the control of the relay which corresponds to the relay R350 and is embodied in the trunk circuit associated with the order trunk on which this call is present.

If a stored order trunk call next to be released from storage by the call storage circuit 31 is abandoned before an order operator's position becomes available the call release switch 510 is automatically advanced to the position corresponding to the next stored call, assuming that additional order trunk calls are in storage. Thus, if a trunk call originating on the trunk 18 is one of a number of order trunk calls in storage, the switch 510 occupies a position corresponding to the call on the trunk 18 and this call is abandoned, the trunk circuit apparatus 19 is caused to be released in the manner previously described. During the release of this apparatus the wipers of the switch 360 are restored to normal under the control of the magnet 369. This homing operation on the part of this switch 360 results in the removal of ground potential from the contact of the set 364 which corresponds to the position occupied by the wipers of the switch 510 and, hence, the relay R550 is de-energized and restores. This relay restoring initiates the cyclic operation of the two relays R570 and R520 and the magnet 517 in the manner previously explained, thus causing the wipers of the switch 510 to be operated step by step until the contacts corresponding to the next stored call are engaged thereby. When the wipers of the switch 510 reach the position corresponding to the next call in storage, the relays R550 and R570 are locked up under the control of the relay corresponding to the relay R350 and embodied in the trunk circuit associated with the order trunk on which the next stored call is present.

In order to prevent useless operation of the switch 500 when more than twenty-three of the call storage positions thereof are occupied with stored calls and to prevent later initiated calls from obtaining preferred storage positions, an arrangement comprising the slip multiple extending between the contact sets 501 and 503 of this switch is provided. More specifically, this slip multiple is such that when the wiper 504 engages any of its associated contacts except the first, it is connected by way of one of the conductors of the multiple to the contact next succeeding the engaged contact and provided in the contact set 503. To this end, the second contact of the set 503, which corresponds to the first storage position of the switch 500, is connected to the twenty-fifth contact of the set 501 and the contacts numbered from 3 to 25, inclusive, of the contact set 503 are respectively connected to the contacts numbered from 2 to 24, inclusive, of the contact set 501. With this arrangement if call storage is started and all but one of the twenty-four available storage positions are subsequently assigned at a time when no order operators' positions are available, the wiper 504 will be connected to a grounded contact in the contact set 503. Thus, if the wipers 504 to 506, inclusive, occupy positions in engagement with their asso-

ciated third contacts when the next to last storage position is filled, these wipers will not be advanced from this position. Under these circumstances if the wipers of the finder switch 360, for example, occupy positions in engagement with their associated fourth contacts, corresponding to the fourth storage position of the switch 500, ground potential is extended from RA325 through the lower winding of R330 and the wiper 367 to the fourth contact of the contact set 503. Accordingly, a circuit is completed for energizing the relay R530, this circuit extending from the grounded fourth contact of the set 503 by way of the third contact of the set 501, the wiper 504, C482, the contacts of the step-on switch 421, C481 and the winding of R530 to battery. The relay R530 operating disconnects ground from the conductor C374 commonly included in the various operating circuits for the motor magnets of the storage position finder switches corresponding to and including the switch 360, thereby to prevent any of these switches which are associated with idle order trunks from being operated. At RA531, the relay R530 opens a point in the above-traced operating circuit for the motor magnet 507, whereby operation of the distributor switch 500 is prevented. With the apparatus in this condition if an order trunk call is initiated, the relays embodied in the trunk circuit associated with this trunk line, which correspond to the relays R300 and R320 of the trunk circuit 19, are caused to operate, the last-mentioned thereof functioning to complete a locking circuit for itself. Following the operation of these two relays the trunk circuit in use remains locked up until the call routed thereover is abandoned or until a call storage position becomes available in the switch 500 through the release of one of the previously stored calls from storage.

The relay R530 remains operated until such time as the stored call corresponding to the storage position of the switch 500 next succeeding that occupied by the wipers of this switch is released from storage. It will be apparent from the foregoing explanation that this stored call will be the next call to be released from storage under the control of the switch 510. When this call, which, as was stated above, is present on the order trunk 18, is released from storage, the relay R320 is caused to release and the switch 360 is automatically restored to its home position, all in the manner previously explained. The relay R320 releasing disconnects ground from the third contact of the contact set 503 in the switch 500 and in so doing interrupts the previously traced operating circuit for the relay R530. The relay R530 releasing, prepares at RA531, the operating circuit for the magnet 507. At RA532, the relay R530 again connects the common conductor C374 to ground so that if an unstored call is present on one of the order trunks a circuit is completed for energizing the motor magnet of the call storage finder switch associated with the trunk on which the unstored call is present. This finder switch operates to advance its wipers into engagement with their associated third contacts at which time the previously described trunk circuit relay operations occur to place the unstored call in storage. Incident to these trunk circuit relay operations, ground potential is impressed upon the third contact of the contact set 503 to cause the sequential operation of the relay R568 and the magnet 507 followed by the release of these two circuit controlling devices,

so that the wipers of the switch 500 are advanced into engagement with their respective associated fourth contacts. At this time ground is again applied over one of the slip multiple conductors to the wiper 504 so that the relay R530 is reoperated to perform the functions previously described. From the foregoing explanation it will be apparent that while twenty-four storage positions are actually provided in the switch 500 only twenty-three of these positions can normally be used simultaneously. It will further be apparent that the slip multiple arrangement between the contact sets 501 and 503 of the switch 500 functions to prevent useless operation of this switch when all of the storage positions are filled and to prevent later initiated order trunk calls from obtaining preferred storage positions in the switch 500, thus insuring the release of the calls from storage in the same order as they are stored.

In order further to prevent unnecessary delay in releasing calls from storage an arrangement is provided for preventing the wipers of the switch 510 from being operated to a position in advance of the position occupied by the wipers of the switch 500. In this regard it will be recalled from the foregoing explanation that when all of the order operators' positions are busy the relay R540 is operated. With this relay operated, if a call originates on the order trunk 18, the relay R320 of the trunk circuit 19 operates to complete the previously traced operating circuit for the relay R520, thereby to initiate the stepping operation of the switch 510. Simultaneously with the initiation of operation of the switch 510, operation of the switch 360 is initiated in the manner previously explained. If the operation of these two switches is initiated at a time when the wipers of the switch 500 are engaging their respective associated twenty-fourth contacts, twenty-four steps on the part of the switch 360 are required to position the wiper 368 on the associated twenty-fourth contact to complete the circuit for energizing the stop relay R550 associated with the switch 510. On the other hand, if the wipers of the switch are engaging their associated twenty-third contacts when operation of the switch 510 is initiated, only three steps are required on the part of the switch 510 in order to advance the wipers of this switch to a position beyond that occupied by the wipers of the switch 500. In such case a complete cycle of operation of the switch 510 is obviously required before the wiper 516 engages the contact in the contact set 513 which has been marked through operation of the switch 360 to cause the operation of the stop relay R550. Although the step-by-step operation of the switch 510 is relatively slow as compared with that of the storage position finder switches individual to the order trunk circuits, it is easily possible for the wipers of the switch 510 to be advanced three or more positions while the wipers of the switch 360 are being advanced through twenty-four or less positions. Hence, it would be possible for a substantial time interval to elapse between the release of an order operator's position and the release of a call from storage.

In order to obviate the difficulties outlined in the preceding paragraph, there is provided an arrangement which comprises a slip multiple extending between the contacts of the contact set 502 embodied in the switch 500 and the contacts of the contact set 511 embodied in the switch 510. More specifically the twenty-fifth

contact of the set 511 is connected to the second contact of the contact set 502 and the contacts numbered from 2 to 24, inclusive, of the contact set 511 are respectively connected to the contacts numbered from 3 to 25, inclusive, of the contact set 502. With this arrangement an alternative circuit is provided for energizing the relay R550 each time the wipers of the switch 510 are advanced to a position one step behind the position occupied by the wipers of the switch 500 at a time when an order trunk call is to be placed in storage. Thus, in the foregoing illustration wherein a call originating on the order trunk 18 is assigned to the twenty-fifth storage position of the switch 500, ground potential is impressed upon the conductor C373 through operation of the relay R320 in the manner previously explained and the stepping operation of the two switches 360 and 510 is substantially 10 simultaneously initiated. When, however, the wipers of the switch 510 have been advanced to engage their associated twenty-fourth contacts the above-mentioned alternative circuit is completed for energizing the relay R550 regardless of the position occupied by the wipers of the switch 360. This alternative circuit extends from ground by way of RA326, C373, the wiper 505 and its associated twenty-fifth contact, the wiper 514 and its associated twenty-fourth contact, and 20 the upper winding of R550 to battery. When this circuit is completed the relay R550 operates to complete the previously traced locking circuit for the relay R570, thereby to arrest the stepping operation of the switch 510 in the manner previously explained. When thereafter the wipers of the switch 500 are advanced to the next succeeding storage position, in the manner previously described, the alternative circuit for energizing the relay R550 is interrupted at the wiper 505 and its associated twenty-fifth contact. By this time, of course, the wipers of the switch 360 have been positioned in engagement with their respective associated twenty-fifth contacts representing the storage position assigned to the 30 trunk circuit 19 by the switch 500. Also, ground potential is still present upon the conductor C373 so that when the relay R550 releases the relays R570 and R520, in cooperation with the operating magnet 517, function to cause the wipers of the switch 510 to be advanced into engagement with their respective associated twenty-fifth contacts. At this time a circuit extending from ground at RA351 and through the wipers 368 and 516 is completed for again energizing the relay 40 R550. This relay in reoperating completes the locking circuit for the relay R570, thereby to prevent further operation of the switch 510. From the foregoing explanation it will be apparent that the provision of the slip multiple between the contact sets 502 and 511 positively precludes the possibility of the wipers of the switch 510 from being advanced to a position ahead of the position occupied by the wipers of the switch 500.

Supervision

As indicated previously, apparatus is provided at the supervisory operator's position 32 whereby this operator may maintain a close check on the condition of the order operators' positions and the volume of traffic routed over the order trunk lines. Thus, provisions are made whereby the operator may monitor any connection involving any one of the order operators' positions. To this end, the jack 491 is provided, the springs of 70 which are connected by way of the conductors

C492 and C493 to opposite sides of the talking conductors forming a part of the apparatus provided at the order operator's position 21. Other jacks are provided which are individually connected to the substation apparatus provided at the other order operators' positions. The lamps 424 and 425 are individual to the operator's position 21 and similar lamps are provided for the other operators' positions. The trunk call storage lamp 426, on the other hand, is individual to the order trunk 18 and associated trunk circuit 19, similar trunk call storage lamps being provided in association with each of the other order trunks. These lamps are so arranged that by observing the condition of the lamp 425 and the corresponding lamps, the supervisory operator is informed as to the number of order operators' positions which are staffed and by observing the condition of the lamp 424 and the other lamps corresponding thereto the supervisory operator is informed as to the number of order operators' positions which are occupied with calls. Finally, by observing the condition of the lamp 426 and the other lamps corresponding thereto the supervisory operator is informed as to the number of calls which are in storage. If, in any case, the supervisory operator desires to monitor a particular order operator's position she may do so by inserting the plug terminating her cord circuit in one of the jacks, such, for example, as the jack 491, thereby to establish a talking circuit directly to the substation apparatus provided at the order operator's position selected.

The supervisory operator may also control the call storage circuit 31. More specifically, if conditions are such that the call storage circuit should not be used or is not required the supervisory operator may operate the no-storage key 422 to its off-normal position so that no circuit is available from the negative terminal of the exchange battery through the resistor 484 to the common conductor C483. With this key in its off-normal position the call storage start relay R540 cannot be energized even though all of the staffed order operators' positions are busy and overflow calls are present on the order trunks. This is true for the reason that with the relay R540 in its restored position, the common lead C371 is disconnected from ground and, accordingly, none of the relays corresponding to and including the relay R320 and embodied in the various trunk circuits can be operated. Under these circumstances, the position finder individual to the trunk circuits associated with order trunks on which overflow calls are present are each operated continuously in search of an idle order operator's position until such time as one of these positions is seized thereby.

Under conditions of extremely heavy traffic wherein a large number of order trunk calls are in storage so that a long waiting interval is involved before each call is routed to an operator's position, many of the stored calls may be abandoned, thus leaving unoccupied storage positions in the bank contacts of the switch 500. Normally, these vacated storage positions can only be utilized in regular order. Under such conditions it may be desirable to fill up the vacated storage positions with calls waiting for storage and also to utilize the twenty-fourth storage position, which normally cannot be used, for the purpose of storing an additional call. These operating facilities are realized in accordance with one feature of the present invention by provid-

ing the step-on key 421 at the supervisory operator's position 32. As previously explained, the contacts of this key are normally engaged to close one point in the operating circuit for the call storage position busy relay R530, so that when the wipers of the switch 500 are operated to a position one step behind another position which corresponds to a stored call, the relay R530 is caused to operate to prevent the storage of further calls. If, under the conditions stated, the key 421 is operated to its off-normal position the operating circuit for the relay R530 is interrupted and this relay restores to reprepare, at RA531, the operating circuit for the magnet 507 and to complete, at RA532, the path for impressing ground potential upon the common motor magnet start conductor C374. If a call is waiting to be stored at the time the relay R530 is released, the call storage finder switch embodied in the trunk circuit associated with the order trunk on which the unstored call exists is operated to a position corresponding to that occupied by the switch 500, whereby the call is stored in the last available storage position of the switch 500. Following the storage of the call in this manner, the relay R560, in cooperation with the magnet 507, functions to advance the wipers 504 to 506, inclusive, step by step over their associated contacts in search of an idle storage position. If certain of the stored calls have been abandoned prior to this searching operation on the part of the switch 500, operation of the switch is arrested when the first of the storage positions corresponding to an abandoned call is reached. More particularly, when the wipers of the switch 500 are moved to engage contacts which correspond to a storage position vacated through abandonment of a call, the operating circuit for the relay R560 is opened at the wiper 506 and the contact engaged thereby, so that operation of the switch 500 is arrested. As additional order trunk calls are initiated, the storage positions of the switch 500 which correspond to calls previously stored but abandoned are filled up in the order in which they are reached by the wipers 504 to 506, inclusive. The supervisory operator attending the position 32 can easily tell when all of the twenty-four available storage positions of the circuit 31 are filled by observing the condition of the call storage lamp 426 and the other similar lamps individual to the order trunks. Thus, when twenty-four of these lamps are energized the supervisory operator is informed that all of the twenty-four available storage positions in the call storage circuit 31 have been filled. If certain of these positions have been filled through operation of the step-on key 421 and this step-on key occupies its off-normal position at the time the twenty-fourth trunk call storage lamp is energized, the supervisory operator should immediately restore the step-on key to its normal position in order to prevent useless continued operation of the switch 500. More specifically, if all of the storage positions of the switch 500 are occupied with stored calls, all of the contacts of the contact sets 501 and 503 are connected to ground. Accordingly, the relay R560 and the magnet 507 will interact continuously to drive the wipers of the switch 500 without interruption until one of the call storage positions is released, either by the release of a call from storage or by the abandonment of a stored call. Under these circumstances, the call storage position selecting switches associated with order trunks on which further calls are initiated will

be caused continuously to operate in search of a storage position by virtue of the presence of ground potential upon the common conductor C374. If, however, the step-on key 421 is restored to normal immediately all of the available call storage positions are filled, the relay R530 is immediately energized and operates to open, at RA531, a point in the operating circuit for the magnet 507, thereby to arrest operation of the switch 500. At RA532, the relay R530 disconnects the conductor C374 from ground, thereby to prevent useless operation of any of the call storage finder switches embodied in the trunk circuits.

In an installation involving apparatus of the character just described, the number of order trunks provided is usually less than the sum of the number of order operators' positions and the total number of storage positions available. With this arrangement, if a substantial portion or all of the order operators' positions are staffed an all-busy condition of the order trunks may occur. In order to indicate this condition there is provided an all-trunks busy meter 522 which is normally short-circuited over the conductor C372 which is common to the order trunk circuits. This common conductor is multiplied to normally grounded contact springs of the line relays individual to the various order trunks. For example, with the line relay R300 restored one of the multiple grounding paths is completed, at RA301 and its associated back contact. Obviously with all of the order trunks occupied with calls all of the multiple grounding paths are open, whereby the conductor C372 is disconnected from ground and the winding of the meter 522 is energized over a circuit including the resistor 523. Thus, each time an all-busy condition of the order trunks prevails, the meter 522 is operated to register the condition.

While there has been described what is at present considered to be the preferred embodiment of the invention, it will be understood that various modifications may be made therein, and it is contemplated to cover in the appended claims all such modifications as fall within the true spirit and scope of the invention.

What is claimed is:

1. In a telephone system comprising a central exchange, a branch exchange including an operator's position and a plurality of trunks extending between said exchanges; additional apparatus for handling calls of a special character routed from said central exchange to the branch exchange area, said apparatus comprising a plurality of special operators' positions, special call trunks extending from said central exchange to said branch exchange area, transfer trunks extending to said branch exchange operator's position, trunk circuits individual to said special call trunks and each including means for routing calls on the associated trunk to idle ones of said special operators' positions, and transfer relays individual to said trunk circuits, each of said transfer relays being controllable from any one of said special operators' positions to split an established talking circuit including the associated trunk and to route the call present on the associated trunk over one of said transfer trunks to said branch exchange operator's position.

2. In a telephone system comprising a central exchange, a branch exchange including an operator's position and a plurality of trunks extending between said exchanges; additional apparatus for handling calls of a special character routed

from said central exchange to the branch exchange area, said apparatus comprising a plurality of special operators' positions, special call trunks extending from said central exchange to said branch exchange area, transfer trunks extending to said branch exchange operator's position, trunk circuits individual to said special call trunks and each including means for routing calls on the associated trunk to idle ones of said special operators' positions, and transfer relays individual to said trunk circuits, each of said transfer relays being controllable from any one of said special operators' positions to split an established talking circuit including the associated trunk and to route the call present on the associated trunk over one of said transfer trunks to said branch exchange operator's position, said transfer relays also being controllable from said special operators' positions to release the respective associated trunk circuits.

3. In a telephone system comprising a central exchange, a branch exchange including an operator's position and a plurality of trunks extending between said exchanges; additional apparatus for handling calls of a special character routed from said central exchange to the branch exchange area, said apparatus comprising a plurality of special operators' positions, special call trunks extending from said central exchange to said branch exchange area, transfer trunks extending to said branch exchange operator's position, signal devices individual to said transfer trunks and located at said branch exchange operator's position, trunk circuits individual to said special call trunks and each including means for routing a call on the associated trunk to an idle one of said special operators' positions, transfer relays individual to said trunk circuits, and circuit means so connected and arranged that each of said transfer relays is controllable from any one of said special operators' positions to split an established talking circuit including the associated trunk and to cause the energization of one of said signal devices.

4. In a telephone system comprising a central exchange, a branch exchange including an operator's position and a plurality of trunks extending between said exchanges; additional apparatus for handling calls of a special character routed from said central exchange to the branch exchange area, said apparatus comprising a plurality of special operators' positions, special call trunks extending from said central exchange to said branch exchange area, transfer trunks extending to said branch exchange operator's position, signal devices individual to said transfer trunks and located at said branch exchange operator's position, trunk circuits individual to said special call trunks and each including a position finder automatically operative to route a call on the associated trunk to an idle one of said special operators' positions, transfer switches individually provided at said special operators' positions, and transfer relays individual to said trunk circuits, each of said transfer relays being operative in response to operation of the transfer switch provided at any one of said special operators' positions which is connected to the associated trunk to split the connection between the associated trunk and the connected operator's position and to energize the signal device at said branch exchange operator's position which corresponds to one of said transfer trunks, whereby a two station connection including said connected special operator's

position and said branch exchange operator's position may be established, said transfer relays also being releasable under the control of said transfer switches to connect the associated trunks to said transfer trunks, whereby three-way connections including said special operator's positions and said branch exchange operators' position may be established.

5. In a telephone system comprising a central exchange, a branch exchange including an operator's position and a plurality of trunks extending between said exchanges; additional apparatus for handling calls of a special character routed from said central exchange to the branch exchange area, said apparatus comprising a plurality of special operators' positions, special call trunks extending from said central exchange to said branch exchange area, transfer trunks extending to said branch exchange operator's position, signal devices individual to said transfer trunks and located at said branch exchange operator's position, trunk circuits individual to said special call trunks and each including a position finder automatically operative to route a call on the associated trunk to an idle one of said special operators' positions, transfer switches individually provided at said special operators' positions, transfer relays individual to said trunk circuits, each of said transfer relays being operative in response to operation of the transfer switch provided at any one of said special operators' positions which is connected to the associated trunk to split the connection between the associated trunk and the connected operator's position and to energize the signal device at said branch exchange operator's position which corresponds to one of said transfer trunks, whereby a two station connection including said connected special operator's position and said branch exchange operator's position may be established, said transfer relays also being releasable under the control of said transfer switches to connect the associated trunks to said transfer trunks, whereby three-way connections including said special operators' positions and said branch exchange operators' positions may be established, and means controllable from said special operators' positions for releasing said special operators' positions for further use after said special calls have been transferred therefrom to said branch operator's position.

6. In a telephone system comprising a central exchange, a branch exchange including an operator's position and a plurality of trunks extending between said exchanges; additional apparatus for handling calls of a special character routed from said central exchange to the branch exchange area, said apparatus comprising a plurality of special operators' positions, special call trunks extending from said central exchange to said branch exchange area, transfer trunks extending to said branch exchange operator's position, signal devices individual to said transfer trunks and located at said branch exchange operator's position, trunk circuits individual to said special call trunks and each including a position finder automatically operative to route a call on the associated trunk to an idle one of said special operators' positions, transfer switches individually provided at said special operators' positions, transfer relays individual to said trunk circuits, each of said transfer relays being operative in response to operation of the transfer switch provided at any one of said special operators' positions which is connected

to the associated trunk to split the connection between the associated trunk and the connected operator's position and to energize the signal device at said branch exchange operator's position which corresponds to one of said transfer trunks, whereby a two station connection including said connected special operator's position and said branch exchange operator's position may be established, said transfer relays also being releasable under the control of said transfer switches to connect the associated trunks to said transfer trunks, whereby three-way connections including said special operators' positions and said branch exchange operator's position may be established, and release switches at said special operators' positions, said transfer relays being operative to release said special operators' positions under the control of said release switches after special calls have been transferred from said special operators' positions to said branch exchange operator's position.

7. In a telephone system comprising a central exchange, a branch exchange including an operator's switchboard and a plurality of trunks extending between said exchanges; additional apparatus for handling calls of a special character routed from said central exchange to the branch exchange area, said apparatus including a plurality of special operators' positions, special call trunks extending from said central exchange to said branch exchange area, trunk circuits individual to said special call trunks and each including means for routing calls on the associated trunk to idle ones of said special operators' positions, and means for routing calls from each of said special operators' positions to said switchboard over any one of a plurality of different routes.

8. In a telephone system comprising a central exchange, a branch exchange including an operator's position and a plurality of trunks extending between said exchanges; additional apparatus for handling calls of a special character routed from said central exchange to said branch exchange area, said additional apparatus comprising special call trunks extending from said central exchange to said branch exchange area, trunk circuits individual to said special call trunks and including means automatically operative to route calls on the associated trunks to idle ones of said special operators' positions, transfer trunks extending to said branch exchange operator's position, means controllable from said special operators' positions for transferring calls from said special operators' positions over said transfer trunks to said branch exchange operator's position, additional trunks extending from said branch exchange operator's position to said special operators' positions, and means controllable from said special operators' positions for routing calls over said additional trunks to said branch exchange operator's position.

9. In a telephone system comprising a central exchange, a branch exchange including an operator's position and a plurality of trunks extending between said exchanges; additional apparatus for handling calls of a special character routed from said central exchange to said branch exchange area, said additional apparatus comprising special call trunks extending from said central exchange to said branch exchange area, trunk circuits individual to said special call trunks and including means automatically operative to route calls on the associated trunks to idle ones

of said special operators' positions, transfer trunks extending to said branch exchange operator's position, means controllable from said special operators' positions for transferring calls from said special operators' positions over said transfer trunks to said branch exchange operator's position, additional trunks extending from said branch exchange operator's position and each terminating in a finder having access to said special operators' positions, a distributor associated with said additional trunks and operative to assign said additional trunks to the use of calling ones of special operators' positions, means controllable from any calling one of said special operators' positions for marking the calling operator's position in said finders and for initiating the operation of the assigned finder to search for said calling operator's position, and means responsive to the operation of said assigned finder to find said calling operator's position for establishing a connection between said calling operator's position and said branch exchange operator's position.

10. In a telephone system comprising a central exchange, a branch exchange including an operator's position and a plurality of trunks extending between said exchanges; additional apparatus for handling calls of a special character routed from said central exchange to said branch exchange area, said additional apparatus comprising special call trunks extending from said central exchange to said branch exchange area, trunk circuits individual to said special call trunks and including means automatically operative to route calls on the associated trunks to idle ones of said special operators' positions, additional trunks extending from said branch exchange operator's position and each terminating in a finder having access to said special operators' positions, a distributor associated with said additional trunks and operative to assign said additional trunks to the use of calling ones of special operators' positions, means controllable from any calling one of said special operators' positions for marking the calling operator's position in said finders and for initiating the operation of the assigned finder to search for said calling operator's position, and means responsive to the operation of said assigned finder to find said calling operator's position for establishing a connection between said calling operator's position and said branch exchange operator's position.

11. In a telephone system comprising a central exchange and a branch exchange including regular branch exchange facilities; additional apparatus for handling calls of a special character routed from said central exchange to said branch exchange, said apparatus comprising a plurality of special operators' positions, a plurality of trunks extending from said central exchange to said branch exchange, and trunk circuits individual to said trunks and each including means operative in direct response to the initiation of a call on the associated trunk to route the call directly to an idle one of said operators' positions.

12. In a telephone system comprising a central exchange and a branch exchange including regular branch exchange facilities; additional apparatus for handling calls of a special character routed from said central exchange to said branch exchange, said apparatus comprising a plurality of special operators' positions, a plurality of trunks extending from said central exchange to said branch exchange, and trunk circuits individual to said trunks and each including a posi-

tion finder having access to said operators' positions and a slow-to-operate relay operative to initiate operation of the associated finder, a relay associated with each trunk and operative to energize the associated slow-to-operate relay in response to a calling signal transmitted over the associated trunk; and finder stopping relays individual to said trunk circuits and each operative to arrest operation of the associated finder when the associated finder selects an idle position, to mark the selected position as busy in the other position finders and to connect the associated trunk through the associated finder to the selected operator's position.

13. In a telephone system comprising a central exchange and a branch exchange including regular branch exchange facilities; additional apparatus for handling calls of a special character routed from said central exchange to said branch exchange, said apparatus comprising a plurality of special operators' positions, a plurality of trunks extending from said central exchange to said branch exchange, and trunk circuits individual to said trunks and each including a position finder having access to said operators' positions and a slow-to-operate relay operative to cause the associated finder to search for an idle one of said positions in response to a call initiated on the associated trunk, and additional relays individual to said trunk circuits and each operative to prevent operation of the associated slow-to-operate relay in response to a call initiated on the associated trunk when all of said operators' positions are busy.

14. In a telephone system comprising a central exchange and a branch exchange including regular branch exchange facilities; additional apparatus for handling calls of a special character routed from said central exchange to said branch exchange, said apparatus comprising a plurality of special operators' positions, a plurality of trunks extending from said central exchange to said branch exchange, and trunk circuits individual to said trunks and each including a position finder having access to said operators' positions and a slow-to-operate relay operative to cause the associated finder to search for an idle one of said positions in response to a call initiated on the associated trunk, and additional relays individual to said trunk circuits and each operative to prevent operation of the associated slow-to-operate relay in response to a call initiated on the associated trunk when all of said operators' positions are busy, and call storage relays individual to said trunk circuits and each operative to prevent operation of the associated slow-to-operate relay in response to a call initiated on the associated trunk when all of said operators' positions are busy, and call storage means controlled by said call storage relays for storing calls initiated on said trunks at a time when all of said operators' positions are busy.

15. In a telephone system comprising a central exchange and a branch exchange including regular branch exchange facilities; additional apparatus for handling calls of a special character routed from said central exchange to said branch exchange, said apparatus comprising a plurality of special operators' positions, a plurality of trunks extending from said central exchange to said branch exchange, and trunk circuits individual to said trunks and each including a position finder having access to said operators' positions and a slow-to-operate relay operative to cause the associated finder to search for an idle one of said positions in response to a call initiated on the associated trunk, and additional relays individual to said trunk circuits and each operative to prevent operation of the associated slow-to-operate relay in response to a call initiated on the associated trunk when all of said operators' positions are busy, and call storage relays individual to said trunk circuits and each operative to prevent operation of the associated slow-to-operate relay in response to a call initiated on the associated trunk when all of said operators' positions are busy.

tiated on the associated trunk when all of said operators' positions are busy, call storage means controlled by said call storage relays for storing calls initiated on said trunks at a time when all of said operators' positions are busy in a predetermined order determined by the sequence of operation of said call storage relays, and means for releasing said calls from storage in said predetermined order as said operators' positions become idle.

16. In a telephone system comprising a central exchange and a branch exchange area including regular branch exchange facilities; additional apparatus for handling calls of a special character routed from said central exchange to said branch exchange area, said apparatus comprising a plurality of special operators' positions, call storage means operative to store calls of said special character initiated at times when all of said positions are busy, means for releasing said stored calls from storage as said positions become idle, and means independent of said call storage means for routing said calls of special character directly to said operators' positions so long as any of said positions are idle.

17. In a telephone system comprising a central exchange and a branch exchange area including regular branch exchange facilities; additional apparatus for handling calls of a special character routed from said central exchange to said branch exchange area, said apparatus comprising a plurality of special operators' positions, call storage means operative to store calls of said special character initiated at times when all of said positions are busy, means for extending said stored calls to idle ones of said operators' positions in the order in which the calls are stored as said positions become idle, and means independent of said call storage means for routing said calls of special character directly to said operators' positions so long as any of said positions are idle.

18. In a telephone system comprising a central exchange and a branch exchange area including regular branch exchange facilities; additional apparatus for handling calls of a special character routed from said central exchange to said branch exchange area, said apparatus comprising a plurality of special operators' positions, trunks extending from said central exchange to said branch exchange area and adapted to have said calls of special character routed thereto, position finder means individual to said trunks, call storage means including a circuit common to said trunks and operative to store calls routed over said trunks at times when all of said positions are busy and to route said stored calls to said positions as said positions become idle, and means independent of said circuit and individual to said trunks for routing said calls of special character by way of said finder means directly to said operators' positions so long as any of said positions are idle.

19. In a telephone system, a central exchange area, a branch exchange area including a plurality of operators' positions for handling calls routed from said central exchange to said branch exchange area, call storage means operative to store calls in excess of the call handling capacity of said positions, and automatic position finder means normally operative independently of said call storage means to route said calls directly to idle ones of said positions so long as any of said positions are idle and operative under the control

of said call storage means to route stored calls to said positions as said positions become idle.

20. In a telephone system comprising a central exchange and a branch exchange area including regular branch exchange facilities; additional apparatus for handling calls of a special character routed from said central exchange to said branch exchange area; said apparatus comprising a plurality of operators' positions, a plurality of trunks extending from said central exchange to said branch exchange area, trunk circuits individual to said trunks and each including finder means having access to said positions, means individual to said trunk circuits and operative in response to the initiation of calls on the associated trunks for initiating operation of the associated finder means in the event any of said positions are idle, a call storage circuit, and means individual to said trunk circuits and operative in cooperation with said storage circuit and in response to the initiation of calls on the associated trunks when all of said positions are busy for storing the calls and for preventing operation of the associated finder means.

21. In a telephone system comprising a central exchange and a branch exchange area including regular branch exchange facilities; additional apparatus for handling calls of a special character routed from said central exchange to said branch exchange area; said apparatus comprising a plurality of operators' positions, a plurality of trunks extending from said central exchange to said branch exchange area, trunk circuits individual to said trunks and each including finder means having access to said positions, means individual to said trunk circuits and operative in response to the initiation of calls on the associated trunks for initiating operation of the associated finder means in the event any of said positions are idle, a call storage circuit, means individual to said trunk circuits and operative in cooperation with said storage circuit and in response to the initiation of calls on the associated trunks when all of said positions are busy for storing the calls and for preventing operation of the associated finder means, and means for releasing the calls from storage in the order of storage as said positions become idle and for routing the calls released from storage through said finder means to said positions.

22. In a telephone system comprising a central exchange and a branch exchange area including regular branch exchange facilities; additional apparatus for handling calls of special character routed from said central exchange to said branch exchange area; said apparatus comprising a plurality of operators' positions, a plurality of trunks extending from said central exchange to said branch exchange area, a call storage circuit including a storage distributor having a plurality of storage positions, trunk circuits individual to said trunks and each including a position finder having access to said operators' positions and a storage finder having positions corresponding to the positions of said storage distributor, means individual to said trunk circuits and operative in response to the initiation of calls on the associated lines to initiate operation of the associated position finders if any of said operators' positions are idle and to initiate operation of the associated storage finders if all of said operators' positions are busy, means operative when all of said operators' positions are busy and controlled by said storage distributor for setting said

storage finders in different positions indicative of the sequence in which said storage finders are operated, and means for initiating operation of the position finders which correspond to operated storage finders in a predetermined order determined by the settings of the respective associated storage finders as said operators' positions become idle.

23. In a telephone system, a plurality of operators' positions, a plurality of trunks, a call storage circuit comprising a call storage distributor switch having a plurality of storage positions and a call release switch having a plurality of release positions, trunk circuits individual to said trunks and each including a finder switch having positions corresponding to the positions of said distributor switch and said release switch, said finder switches being operative in response to calls initiated on the associated trunks when all of said operators' positions are busy, means controlled by said distributor switch for stopping said finder switches in different positions, whereby said calls are stored in a predetermined order, and means jointly controlled by said finder switches and said release switch for routing said stored calls to said operators' positions as said operators' positions become idle in a predetermined order determined by the settings of said finder switches.

24. In a telephone system, a plurality of operators' positions, a plurality of trunks, a call circuit comprising a call storage distributor switch having a plurality of storage positions and a call release switch having a plurality of release positions, trunk circuits individual to said trunks and each including a finder switch having positions corresponding to the positions of said distributor switch and said release switch, said finder switches being operative in response to calls initiated on the associated trunks when all of said operators' positions are busy, means controlled by said distributor switch for stopping said finder switches in different positions, whereby said calls are stored in a predetermined order, means operative in response to each release of one of said operators' positions for routing to the released operator's position the stored call which is present on the trunk corresponding to the finder switch having a setting corresponding to the setting of said release switch, and means for operating said release switch to the position corresponding to the next stored call each time one of said stored calls is routed to one of said operators' positions, whereby said stored calls are routed to said operators' positions in the same order as they are stored.

25. In a telephone system, a plurality of operators' positions, a plurality of trunks, a call storage distributor switch having a plurality of storage positions and a call release switch having a plurality of release positions, trunk circuits individual to said trunks and each including a finder switch having positions corresponding to the positions of said distributor switch and said release switch, each of said finder switches being operative to the position corresponding to the position of said distributor switch in response to the initiation of a call on the associated trunk at a time when all of said operators' positions are busy, means responsive to the operation of each operated finder switch for operating said distributor switch to a new storage position, whereby said finder switches are operated to different positions to store overflow calls initiated on said trunks, and means jointly controlled by said finder

5 switches and said release switch for routing said stored calls to said operators' positions as said operators' positions become idle and in a predetermined order determined by the settings of said finder switches.

26. In a telephone system, a plurality of operators' positions, a plurality of trunks, a call storage distributor switch having a plurality of storage positions and a call release switch having a plurality of release positions, trunk circuits individual to said trunks and each including a finder switch having positions corresponding to the positions of said distributor switch and said release switch, each of said finder switches being operative to the position corresponding to the position of said distributor switch in response to the initiation of a call on the associated trunk at a time when all of said operators' positions are busy, means responsive to the operation of each operated finder switch for operating said distributor switch to a new storage position, whereby said finder switches are operated to different positions to store overflow calls initiated on said trunks, means operative in response to each release of one of said operators' positions for routing to the released operator's position the stored call which is present on the trunk corresponding to the finder switch having a setting corresponding to the setting of said release switch, and means for operating said release switch to the position corresponding to the next stored call each time one of said stored calls is routed to one of said operators' positions, whereby said stored calls are routed to said operators' positions in the same order as they are stored.

27. In a telephone system, a plurality of operators' positions, a plurality of trunks, trunk circuits individual to said trunks and including means normally operative to route calls on the associated trunks directly to idle ones of said operators' positions, a call storage circuit including a distributor having different storage positions and operative to different storage positions in response to succeeding calls initiated on said trunks at a time when all of said operators' positions are busy, means normally operative to prevent further operation of said distributor after a predetermined number of calls have been stored, means for rendering said last-named means inactive, thereby to permit the storage positions corresponding to abandoned stored calls to be utilized in storing additional calls, and means for releasing said calls from storage as said operators' positions become idle.

28. In a telephone system, a plurality of operators' positions, a plurality of trunks, trunk circuits individual to said trunks and including means normally operative to route calls on the associated trunks directly to idle ones of said operators' positions, a call storage circuit including a distributor having different storage positions and operative to different storage positions in response to succeeding calls initiated on said trunks at a time when all of said operators' positions are busy, means controlled in accordance with the operation of said distributor for releasing said calls from storage in the same order as they are stored as said operators' positions become idle, and means for preventing said distributor from operating to a storage position rendered idle through abandonment of a stored call and located between two occupied storage positions, thereby to prevent later initiated calls from obtaining preferred storage positions.

29. In a telephone system, a plurality of oper-

ators' positions, a plurality of trunks, trunk circuits individual to said trunks and including means normally operative to route calls on the associated trunks directly to idle ones of said operators' positions, a call storage circuit including a distributor having different storage positions and operative to different storage positions in response to succeeding calls initiated on said trunks at a time when all of said operators' positions are busy, means controlled in accordance with the operation of said distributor for releasing said calls from storage in the same order as they are stored as said operators' positions become idle, means for preventing said distributor from operating to a storage position rendered idle through abandonment of a stored call and located between two occupied storage positions, thereby to prevent later initiated calls from obtaining preferred storage positions, and means for rendering said last-named means inactive, thereby to permit the storage positions corresponding to abandoned calls to be utilized in storing additional calls.

30. In a telephone system, a plurality of operators' positions, a plurality of trunks, trunk circuits individual to said trunks and including means normally operative to route calls on the associated trunks directly to idle ones of said operators' positions, a call storage circuit including a distributor switch having a plurality of sets of contacts including corresponding contact points representing different storage positions, means for operating said switch to succeeding storage positions in response to successive calls initiated on said trunks at a time when all of said operators' positions are busy, means for releasing said calls from storage as said operators' positions become idle, a slip multiple extending between the contacts of two of said contact sets, a control device operative to prevent operation of said switch, and a circuit including said slip multiple for energizing said control device after a predetermined number of calls have been stored.

31. In a telephone system, a plurality of operators' positions, a plurality of trunks, trunk circuits individual to said trunks and including means normally operative to route calls on the associated trunks directly to idle ones of said operators' position, a call storage circuit including a distributor switch having a plurality of sets of contacts including corresponding contact points representing different storage positions, means for operating said switch to succeeding storage positions in response to successive calls initiated on said trunks at a time when all of said operators' positions are busy, means for releasing said calls from storage as said operators' positions become idle, a slip multiple extending between the contacts of two of said contact sets, a relay operative to prevent operation of said switch, a circuit including said slip multiple for energizing said relay after a predetermined number of calls have been stored, and operator controlled means for opening said circuit, thereby to prevent said relay from operating.

32. In a telephone system, a plurality of operators' positions, a plurality of trunks, trunk circuits individual to said trunks and including means normally operative to route calls on the associated trunks directly to idle ones of said operators' positions, a call storage circuit including a distributor switch having a plurality of sets of contacts including corresponding contact points representing different storage positions, means for operating said switch to succeeding

storage positions in response to successive calls initiated on said trunks at a time when all of said operators' positions are busy, means for releasing said calls from storage as said operators' positions become idle, a slip multiple extending between the contacts of two of said contact sets, a control device operative to prevent operation of said switch, and a circuit including said slip multiple for energizing said control device, said slip multiple being so connected and arranged that said control device is energized when said switch is operated to a position adjacent an occupied storage position, whereby said switch is prevented from operating to a storage position rendered idle through abandonment of a call and located between two occupied storage positions.

33. In a telephone system, a plurality of operators' positions, a plurality of trunks, trunk circuits individual to said trunks and including means normally operative to route calls on the associated trunks directly to idle ones of said operators' positions, a call storage circuit including a distributor switch having a plurality of sets of contacts including corresponding contact points representing different storage positions, means for operating said switch to succeeding storage positions in response to successive calls initiated on said trunks at a time when all of said operators' positions are busy, means for releasing said calls from storage as said operators' positions become idle, a slip multiple extending between the contacts of two of said contact sets, a control device operative to prevent operation of said switch, a circuit including said slip multiple for energizing said control device, said slip multiple being so connected and arranged that said control device is energized when said switch is operated to a position adjacent an occupied storage position, whereby said switch is prevented from operating to a storage position rendered idle through abandonment of a call and located between two occupied storage positions, and operator controlled means for opening said circuit to prevent operation of said control device thereby to permit the storage positions corresponding to calls which have been abandoned to be utilized in storing additional calls.

34. In a telephone system, a plurality of operators' positions, a plurality of trunks, a call storage circuit including a distributor having a plurality of storage positions and operative to different storage positions in response to succeeding calls initiated on said trunks at a time when all of said operators' positions are busy, trunk circuits individual to said trunks and each including means normally operative to route calls on the associated trunks directly to idle ones of said operators' positions, each of said trunk circuits including a storage finder having a normal position and a plurality of positions corresponding to the storage positions of said distributor, said storage finders being operative in response to calls initiated on the associated trunks when all of said operators' positions are busy, means for stopping said finders in different storage positions determined by the operation of said distributor, means controlled in accordance with the settings of said finders for releasing said calls from storage in a predetermined order, means responsive to the abandonment of one of said stored calls for restoring the associated finder to its normal position, thereby to release the corresponding storage position, and means normally operative to prevent said distributor from being operated

through an occupied storage position to the position which has been released.

35. In a telephone system, a plurality of operators' positions, a plurality of trunks, a call storage circuit including a distributor having a plurality of storage positions and operative to different storage positions in response to succeeding calls initiated on said trunks at a time when all of said operators' positions are busy, trunk circuits individual to said trunks and each including means normally operative to route calls on the associated trunks directly to idle ones of said operators' positions, each of said trunk circuits including a storage finder having a normal position and a plurality of positions corresponding to the storage positions of said distributor, said storage finders being operative in response to calls initiated on the associated trunks when all of said operators' positions are busy, means for stopping said finders in different storage positions determined by the operation of said distributor, means controlled in accordance with the settings of said finders for releasing said calls from storage in a predetermined order, means responsive to the abandonment of one of said stored calls for restoring the associated finder to its normal position, thereby to release the corresponding storage position, means normally operative to prevent said distributor from being operated through an occupied storage position to the position which has been released, and means for rendering said last-named means inactive, thereby to permit the storage positions corresponding to abandoned calls to be utilized in storing additional calls.

36. In a telephone system, a plurality of operators' positions, a plurality of trunks, a call storage circuit comprising a distributor having a plurality of storage positions and storage release means having a plurality of positions, said distributor being operative to different storage positions in response to succeeding calls initiated on said trunks at a time when all of said operators' positions are busy, trunk circuits individual to said trunks and each including means normally operative to route calls on the associated trunks directly to idle ones of said operators' positions, each of said trunk circuits including a storage finder having a normal position and a plurality of positions corresponding to the positions of said distributor and said storage release means, said finders being operative in response to calls initiated on the associated trunks when all of said operators' positions are busy, means for stopping said finders in different storage positions determined by the operation of said distributor, means jointly controlled by said storage finders and said storage release means for releasing said calls from storage in a predetermined order determined by the settings of said finders, means responsive to the abandonment of one of said stored calls for restoring the associated finder to its normal position, thereby to release the corresponding storage position, and means normally operative to prevent said distributor from being operated through an occupied storage position to the storage position which has been released.

37. In a telephone system, a plurality of operators' positions, a plurality of trunks, a call storage circuit comprising a distributor having a plurality of storage positions and storage release means having a plurality of positions, said distributor being operative to different storage positions in response to succeeding calls initiated on said trunks at a time when all of said op-

erators' positions are busy, trunk circuits individual to said trunks and each including means normally operative to route calls on the associated trunks directly to idle ones of said operators' positions, each of said trunk circuits including a storage finder having a normal position and a plurality of positions corresponding to the positions of said distributor and said storage release means, said finders being operative in response to calls initiated on the associated trunks when all of said operators' positions are busy, means for stopping said finders in different storage positions determined by the operation of said distributor, means jointly controlled by said storage finders and said storage release means for releasing said calls from storage in a predetermined order determined by the settings of said finders, means responsive to the abandonment of one of said stored calls for restoring the associated finder to its normal position, thereby to release the corresponding storage position, means normally operative to prevent said distributor from being operated through an occupied storage position to the storage position which has been released, and means for rendering said last-named means inactive, thereby to permit the storage positions corresponding to abandoned calls to be utilized in storing additional calls.

38. In a telephone system, a plurality of operators' positions, a plurality of trunks, trunk circuits individual to said trunks and including means normally operative to route calls on the associated trunks directly to idle ones of said operators' positions, a call storage circuit including a storage distributor switch operative to cause calls on said trunks in excess of the call handling capacity of said operators' positions to be stored in a predetermined order and a storage release switch operative to cause stored calls to be released from storage in a predetermined order, said switches having corresponding positions, means for preventing said release switch from operating to a position in advance of that occupied by said distributor switch, and means normally operative to prevent said distributor switch from operating through a position occupied by said release switch.

39. In a telephone system, a plurality of operators' positions, a plurality of trunks, trunk circuits individual to said trunks and including means normally operative to route calls on the associated trunks directly to idle ones of said operators' positions, a call circuit including a storage distributor switch operative to cause calls on said trunks in excess of the call handling capacity of said operators' positions to be stored in a predetermined order and a storage release switch operative to cause stored calls to be released from storage in a predetermined order, said switches having corresponding positions, means for preventing said release switch from operating to a position in advance of that occupied by said distributor switch, means normally operative to prevent said distributor switch from operating through a position occupied by said release switch, and means for rendering said last-named means inactive.

40. In a telephone system, a plurality of operators' positions, a plurality of trunks, trunk circuits individual to said trunks and including means normally operative to route calls on the associated trunks directly to idle ones of said operators' positions, a call storage circuit including a storage distributor switch operative to cause calls on said trunks in excess of the call

handling capacity of said operators' positions to be stored in a predetermined order and a storage release switch operative to cause stored calls to be released from storage in a predetermined order, said switches having corresponding positions, and means for preventing either of said switches from operating through a position occupied by the other switch.

41. In a telephone system, a plurality of operators' positions, a plurality of trunks, trunk circuits individual to said trunks and including means normally operative to route calls on the associated trunks directly to idle ones of said operators' positions, a call storage circuit including a distributor switch and a release switch, said distributor switch including a plurality of contact sets having corresponding contact points representing different storage positions and being operative to different storage positions to cause calls on said trunks in excess of the call handling capacity of said operators' positions to be stored in a predetermined order, said release switch including a plurality of contact sets having corresponding contact points representing different call release positions which correspond to said call storage positions and being operative to different call release positions to cause the release of said calls from storage in a predetermined order as said operators' positions become idle, a slip multiple extending between two of the sets of contacts of said distributor switch, a control device operative to prevent operation of said distributor switch, a circuit including said slip multiple for energizing said control device after a predetermined number of calls have been stored, a second slip multiple extending between a set of contacts of said distributor switch and a set of contacts of said release switch, a second control device operative to prevent operation of said release switch, and a circuit including said second slip multiple for energizing said second control device in response to operation of said release switch to a predetermined position behind the position occupied by said distributor switch.

42. In a telephone system, a plurality of operators' positions, a plurality of trunks, trunk circuits individual to said trunks and including means normally operative to route calls on the associated trunks directly to idle ones of said operators' positions, a call storage circuit including a distributor switch and a release switch, said distributor switch including a plurality of contact sets having corresponding contact points representing different storage positions and being operative to different storage positions to cause calls on said trunks in excess of the call handling capacity of said operators' positions to be stored in a predetermined order, said release switch including a plurality of contact sets having corresponding contact points representing different call release positions which correspond to said call storage positions and being operative to different call release positions to cause the release of said calls from storage in a predetermined order as said operators' positions become idle, a slip multiple extending between two of the sets of contacts of said distributor switch, a control device operative to prevent operation of said distributor switch, a circuit including said slip multiple for energizing said control device, said slip multiple being so connected and arranged that said control device is energized when said distributor switch is operated to a position adjacent an occupied storage position, whereby said distributor switch is prevented from operating to a storage position rendered idle through abandonment of a call and located between two occupied storage positions, operator controlled means for opening said circuit to prevent operation of said control device, thereby to permit the storage positions corresponding to stored calls which have been abandoned to be utilized in storing additional calls, a second slip multiple extending between a set of contacts of said distributor switch and a set of contacts of said release switch, a second control device operative to prevent operation of said release switch, and a circuit including said second slip multiple for energizing said second control device in response to operation of said release switch to a predetermined position behind the position occupied by said distributor switch.

43. In a telephone system, a plurality of operators' positions, a plurality of trunks, trunk circuits individual to said trunks and including means normally operative to route calls on the associated trunks directly to idle ones of said operators' positions, a call storage circuit including a distributor switch and a release switch, said distributor switch including a plurality of contact sets having corresponding contact points representing different storage positions and being operative to different storage positions to cause calls on said trunks in excess of the call handling capacity of said operators' positions to be stored in a predetermined order, said release switch including a plurality of contact sets having corresponding contact points representing different call release positions which correspond to said call storage positions and being operative to different call release positions to cause the release of said calls from storage in a predetermined order as said operators' positions become idle, a slip multiple extending between two of the sets of contacts of said distributor switch, a control device operative to prevent operation of said distributor switch, a circuit including said slip multiple for energizing said control device, said slip multiple being so connected and arranged that said control device is energized when said distributor switch is operated to a position adjacent an occupied storage position, whereby said distributor switch is prevented from operating to a storage position rendered idle through abandonment of a call and located between two occupied storage positions, a second slip multiple extending between a set of contacts of said distributor switch and a set of contacts of said release switch, a second control device operative to prevent operation of said release switch, and a circuit including said second slip multiple for energizing said second control device in response to operation of said release switch to a predetermined position behind the position occupied by said distributor switch.

44. In a telephone system, a plurality of operators' positions, a plurality of trunks, trunk circuits individual to said trunks and including means normally operative to route calls on the associated trunks directly to idle ones of said operators' positions, a call storage circuit including a storage distributor switch operative to cause calls on said trunks in excess of the call handling capacity of said operators' positions to be stored in a predetermined order and a storage release switch operative to cause stored calls to be released from storage in a predetermined order, said switches having corresponding positions, and means for preventing said release switch

70

from operating through a position occupied by said distributor switch.

45. In a telephone system, a plurality of operators' positions, a plurality of trunks, trunk circuits individual to said trunks and including means normally operative to route calls on the associated trunks directly to idle ones of said operators' positions, a call storage circuit including a distributor switch and a release switch, said distributor switch including a plurality of contact sets having corresponding contact points representing different storage positions and being operative to different storage positions to cause calls on said trunks in excess of the call handling capacity of said operators' positions to be stored in a predetermined order, said release switch including a plurality of contact sets having corresponding contact points representing different call release positions which correspond to said call storage positions and being operative to different call release positions to cause the release of said calls from storage in a predetermined order as said operators' positions become idle, a slip multiple extending between a set of contacts of said distributor switch and a set of contacts of said release switch, a control device operative to prevent operation of said release switch, and a circuit including said slip multiple for energizing said control device in response to operation of said release switch to a predetermined position behind the position occupied by said distributor switch.

46. A call storage circuit for use in a telephone system and comprising a pair of distributors respectively operative to determine the order of call storage and the order of releasing calls from storage, said distributors having a plurality of corresponding settings, means for operating said distributors, and means for preventing one of said distributors from operating through a setting occupied by the other distributor.

47. A call storage circuit for use in a telephone system and comprising a pair of distributors respectively operative to determine the order of call storage and the order of releasing calls from storage, said distributors having a plurality of corresponding settings, means for controlling said distributors to store calls in a predetermined order and to release calls from storage in the same order, and means for preventing either of said distributors from operating through a setting occupied by the other distributor.

48. A call storage circuit for use in a telephone system and comprising a pair of distributor switches each including a plurality of sets of contacts having corresponding contact points representing different storage positions, one of said switches being operative to determine the order of call storage and the other of said switches being operative to determine the order of releasing calls from storage, means for controlling said switches to store calls in a predetermined order and to release calls from storage in the same order, and means comprising a device controlled over a slip multiple extending between two of the sets of contacts of said one switch for preventing said one switch from operating through a position occupied by said other switch.

49. A call storage circuit for use in a telephone system and comprising a pair of distributor switches each including a plurality of sets of contacts having corresponding contact points representing different storage positions, one of said switches being operative to determine the order of call storage and the other of said

switches being operative to determine the order of releasing calls from storage, means for controlling said switches to store calls in a predetermined order and to release calls from storage in the same order, and means comprising a device controlled over a slip multiple extending between one of the sets of contacts of said one switch and one of the sets of contacts of said other switch for preventing said other switch from operating through a position occupied by said one switch.

50. A call storage circuit for use in a telephone system and comprising a pair of distributor switches each including a plurality of sets of contacts having corresponding contact points representing different storage positions, one of said switches being operative to determine the order of call storage and the other of said switches being operative to determine the order of releasing calls from storage, means for controlling said switches to store calls in a predetermined order and to release calls from storage in the same order, means comprising a device controlled over a slip multiple extending between two of the sets of contacts of said one switch for preventing said one switch from operating through a position occupied by said other switch, and means comprising a device controlled over a slip multiple extending between one of the sets of contacts of said one switch and one of the sets of contacts of said other switch for preventing said other switch from operating through a position occupied by said one switch.

51. In a telephone system, a plurality of operators' positions, a plurality of trunks, means for routing calls on said trunks to idle ones of said operators' positions, call storage means for storing calls initiated on said trunks when all of said operators' positions are busy and for releasing said calls from storage, another operators' position, and means controllable from said other operator's position for rendering said call storage means inactive.

52. In a telephone system, a plurality of operators' positions, a plurality of trunks, means for routing calls on said trunks to idle ones of said operators' positions, call storage means for storing calls initiated on said trunks when all of said operators' positions are busy and for releasing said calls from storage in the same order as they are stored, a supervisory operator's position, and signal means at said supervisory operator's position for identifying the trunks which are occupied with stored calls.

53. In a telephone system, a plurality of operators' positions, a plurality of trunks, trunk circuits individual to said trunks and including position finder means normally operative to route calls on the associated trunks directly to idle ones of said operators' positions, call storage means for storing calls initiated on said trunks at a time when all of said operators' positions are busy and for releasing said calls from storage in the same order as they are stored, each of said trunk circuits including a call storage relay operative to prevent operation of the associated finder means and to cause the storage of a call initiated on the associated trunk when all of said positions are busy, a supervisory operator's position, and signal devices individually corresponding to said trunks and located at said supervisory operator's position, each of said signal devices being energized in response to operation of the corresponding storage relay.

54. In a telephone system, a plurality of oper-

ators' positions, a plurality of trunks, trunk circuits individual to said trunks and including means normally operative to route calls on the associated trunks directly to idle ones of said operators' positions, a call storage circuit including a distributor having different storage positions and operative to different storage positions in response to succeeding calls initiated on said trunks at a time when all of said operators' positions are busy, a supervisory operator's position, signal means at said supervisory operator's position for indicating the number of trunks occupied with stored calls, means normally operative to prevent further operation of said distributor after a predetermined number of calls have been stored, and means controllable from said supervisory operator's position for rendering said last-named means inactive, thereby to permit the storage positions corresponding to abandoned calls to be utilized in storing additional calls.

55. In a telephone system, a plurality of operators' positions, a plurality of trunks, trunk circuits individual to said trunks and including means normally operative to route calls on the associated trunks directly to idle ones of said operators' positions, a call storage circuit including a distributor having different storage positions and operative to different storage positions in response to succeeding calls initiated on said trunks at a time when all of said operators' positions are busy, a supervisory operator's position, signal means at said supervisory operator's position for indicating the number of trunks occupied with stored calls, means for preventing said distributor from operating to a storage position rendered idle through abandonment of a stored call and located between two occupied storage positions, thereby to prevent later initiated calls from obtaining preferred storage positions, and means controllable from said supervisory operator's position for rendering said last-named means inactive, thereby to permit the storage positions corresponding to abandoned calls to be utilized in storing additional calls.

56. In a telephone system, a plurality of operators' positions, a plurality of trunks, trunk circuits individual to said trunks and including means normally operative to route calls on the associated trunks directly to idle ones of said operators' positions, a call storage circuit including a distributor having different storage positions and operative to different storage positions in response to succeeding calls initiated on said trunks at a time when all of said operators' positions are busy, a supervisory operator's position, signal means at said supervisory operator's position for indicating the number of trunks occupied with stored calls, means controlled in accordance with the operation of said distributor for causing release of said calls from storage in the same

order as they are stored, said signal means being operative to indicate when said calls are released from storage or abandoned, means normally operative to prevent said distributor from operating to a storage position rendered idle through abandonment of a stored call and located between two occupied storage positions, thereby to prevent later initiated calls from obtaining preferred storage positions, and means controllable from said supervisory operator's position for rendering said last-named means inactive, thereby to permit the storage positions corresponding to abandoned calls to be utilized in storing additional calls.

57. In a telephone system, a plurality of operators' positions, a plurality of trunks, a call storage circuit comprising a distributor having a plurality of storage positions and storage release means having a plurality of positions, said distributor being operative to different storage positions in response to succeeding calls initiated on said trunks at a time when all of said operators' positions are busy, trunk circuits individual to said trunks and each including means normally operative to route calls on the associated trunks directly to idle ones of said operators' positions, each of said trunk circuits including a storage finder having a normal position and a plurality of positions corresponding to the positions of said distributor and said storage release means, call storage relays individual to said trunk circuits and operative in response to calls initiated on the associated trunks when all of said operators' positions are busy to initiate operation of the associated finders, means for stopping said finders in different positions determined by the operation of said distributor, means jointly controlled by said call finders and said storage release means for releasing said calls from storage in a predetermined order determined by the settings of said finders, said storage relays being operative to cause the associated finders to be restored to normal when stored calls on the associated trunks are abandoned, thereby to release the corresponding storage positions of said distributor, a supervisory operator's position, signal devices at said supervisory operator's position individually corresponding to said trunks and each energized in response to operation of the associated storage relay, means normally operative to prevent said distributor from being operated through an occupied storage position to a storage position which has been released, and means controllable from said supervisory operator's position for rendering said last-named means inactive, thereby to permit the storage positions corresponding to abandoned stored calls to be utilized in storing additional calls.

CERTIFICATE OF CORRECTION.

Patent No. 2,249,486.

July 15, 1941.

IMRE MOLNAR.

It is hereby certified that error appears in the printed specification of the above numbered patent requiring correction as follows: Page 18, first column, line 6-7, claim 4, for "operator's" read --operators'--; and line 7-8, same claim, for "operators'" read --operator's--; page 24, second column, line 44-45, claim 43, for "abondonment" read --abandonment--; and that the said Letters Patent should be read with this correction therein that the same may conform to the record of the case in the Patent Office.

Signed and sealed this 26th day of August, A. D. 1941.

Henry Van Arsdale,
Acting Commissioner of Patents.
